This invention relates to a calculating machine, and particularly to an improved multiplying mechanism therefor.

It is one primary object of the present invention to provide a multiplying mechanism (which can be used in conjunction with the multiplying mechanism described in the patents to Friden, Nos. 2,371,752 of March 20, 1945 or 2,399,917 of May 7, 1946), which is particularly adapted to use a value in a register, such as the storage, or back-transfer, register disclosed in the patent of Arthur J. Malavazos, No. 3,045,907, issued July 24, 1962, as the multiplier while using a factor standing in the keyboard as a multiplicand.

Another primary and important object of the present invention is to provide a "squaring" machine, in which a factor inserted in the main keyboard of a calculating machine is multiplied by itself—in this instance the keyboard value being set from the keyboard into the auxiliary, or storage, register (which, in our present invention, is the multiplier register) without conventional clearing of the keyboard, so that a subsequent depression of a multiplier control key will be effective to multiply the factor by itself.

Another object of the present invention is to provide duplicate multiplying mechanisms, so that a multiplicand factor standing in the keyboard of the machine can be multiplied by a factor inserted in a conventional multiplier storage device, such as those described in the Friden patents above-mentioned; or selectively, at the will of the operator, to use a product or a quotient which has been registered in the accumulator, or product register, or alternatively in the counter, or quotient register, of a conventional calculating machine. In its preferred form the two multiplier mechanisms are independent, although they use the same controls and are operated by the same

2

multiplier control keys. In this instance, the two multiplying mechanisms are interlocked so that one, and only one, of the two mechanisms can control a particular operation. In its preferred form, the multiplication mechanism utilizes the operating controls of the Friden patents above-mentioned, and also the three manually operated keys which are effective to initiate multiplication preceded by a clearing of the product register, multiplication without such clearing (commonly called "accumulative multiplication"), and multiplication without clearing but with the machine operative subtractively rather than additively (commonly called "negative multiplication") in order to subtract one product from another already in the register.

In its preferred form, our invention utilizes a calculating machine of the type disclosed in the patent to Friden, No. 2,229,889, issued January 28, 1941, as modified by the two Friden patents previously mentioned, and the patent of Malavazos No. 3,045,907, which also has been previously mentioned. The calculator of those patents includes two conventional registers: the accumulator, or product, register and the counter, or quotient, register. The above-mentioned Malavazos patent adds a third, or storage register, and a mechanism whereby factors accumulated in either of the conventional registers can be transferred into the storage register, or into the selection mechanism, or both, at the discretion of the operator. The present invention, in its preferred form, adds a multiplier mechanism to the storage register, so that factors standing in this register may be used as a multiplier factor in a subsequent operation. Thus we provide in one machine a mechanism which greatly extends the usefulness of the conventional calculator, not only by adding an additional register thereto, but also by providing a mechanism by means of which a value transferred from either the conventional accumulator or counter register may be used selectively, at the will of the operator, either as a multiplicand or a multiplier.

Another important object of the present invention, therefore, is to provide a mechanism by means of which the factor storage, or back transfer, register can be used as a multiplier to control a multiplication operation.

The present invention is concerned with these primary objects and others which will become apparent from a perusal of the description of the preferred embodiment of the invention, which is shown in the accompanying drawings and in which:

FIG. 1 is a plan view of the machine with which our invention is preferably associated.

FIG. 2 is a longitudinal cross-sectional view of the rear portion of the machine, showing particularly the selection, actuating and register mechanisms of the machine shown in FIG. 1, and preferably of the first order thereof, such as taken along the plane indicated by the line 2—2 of FIG. 1.

FIG. 3 is a rear view of the carriage shifting and register clearing mechanisms with the cover removed, such as taken along the plane indicated by the line 3—3 of FIG. 1.

FIG. 4 is a cross-sectional plan view of the machine taken on a plane parallel to the keyboard, with the keyboard removed, and shows particularly the clearing and shifting mechanisms of the present invention.

FIG. 5 is a right-hand view of the control mechanisms on the right side of the machine, with the cover removed, such as taken along the plane indicated by the line 5—5 of FIG. 1.

FIG. 6 is a cross-sectional view of mechanism mounted on the right side control plate (which lies immediately to the right of the plane of FIG. 2).

FIG. 7 is a right side view of details of the keyboard assembly.

FIG. 8 is a left side view of mechanism mounted upon, and lying immediately adjacent to, the right side frame; and, in effect, is the reverse side of mechanism shown in FIG. 6.

FIG. 9 is a front view showing details of the multiplication control key and associated mechanism, such as taken from the transverse plane indicated by the line 9—9 of FIG. 8.

FIG. 10 is a left side view of the automatic shifting and clearing mechanism conventionally placed in the machine with which our invention is associated, showing certain modifications thereof required by our invention, and is taken along an intermediate plane, such as that indicated by the line 10—10 of FIG. 4.

FIG. 11 is a right side view of the assembly of mechanisms shown in FIG. 10, such as that taken along the plane indicated by the line 11—11 of FIGS. 4.

FIG. 12 is a right side view of the mechanism mounted upon, or lying immediately adjacent to, the left side frame of the machine, such as that taken along the plane indicated by the line 12—12 of FIG. 1.

FIG. 13 is a front detail of the squaring key taken along the transverse plane indicated by the line 13—13 of FIG. 12, which, in effect, is an extension of the plane 9—9 of FIG. 8, so that, in effect, FIG. 13 constitutes the left-hand extension of the mechanism shown in FIG. 9.

FIG. 14 is a plan view of the mechanism of the left-hand side of the machine and approximately is taken along the same plane as that used in FIG. 4, so that FIG. 14 can be considered as an extension of FIG. 4.

FIG. 15 is a left side view of the multiplier control mechanism taken on planes intermediate left side frame and the left side control plate, as indicated by the lines 15—15 of FIG. 14, and, for the most part, shows mechanism conventional in machines of this kind.

FIG. 16 is a plan view of a detail of the shift control mechanism, such as taken along the plane indicated by the line 16—16 of FIG. 19.

FIG. 17 is a left side view of the left-hand control plate showing, for the most part, conventional multiplying mechanisms in the machine of the present invention, such as taken along a plane lying slightly to the right of that indicated by line 26—26 in FIG. 14.

FIG. 18 is a right side view of the means for disabling the conventional multiplier counting mechanism and enabling that associated with the present invention, such as taken along the longitudinal plane indicated by the line 18—18 of FIG. 14.

FIG. 19 is a right side view of a detail of mechanism for disabling the conventional multiplier carriage shift mechanism, and is taken along the plane indicated by the line 19—19 of FIG. 14.

FIG. 20 is a plan view of the front of the machine shown in FIG. 1, showing the storage register dials and the multiplication mechanism associated therewith.

FIG. 21 is a front view of the mechanism shown in FIG. 20.

FIG. 22 is a left side view of the first order of the multiplication mechanism shown in FIGS. 20 and 21, such as taken along the plane indicated by the line 22—22 of FIG. 20.

FIG. 23 is a left side view of control mechanisms lying to the left of the multiplication mechanism, such as taken along the plane indicated by the line 23—23 of FIG. 21.

FIG. 24 is a right side and enlarged view of the highest order of the mechanism shown in FIG. 20.

FIG. 25 is an enlarged front view of one order of the left-hand side of the multiplication mechanism shown in FIG. 20.

FIG. 26 is a left side view of the machine of the present invention, showing the new multiplication controls superimposed over the conventional mechanism shown in FIG. 17, and is taken along the plane indicated by the line 26—26 of FIG. 14.

FIG. 27 is a detail of the restore mechanism and check pawl associated with the present invention, and is taken along the planes indicated by the lines 27—27 in FIG. 14; and

FIG. 28 is a left side view similar to that shown in FIG. 26 but with the mechanisms adjusted for a multiplication operation under the control of the front storage dials.

I. CONVENTIONAL MECHANISMS

The present invention is applied, for purposes of exemplification, to a calculating machine of the general type shown and described in the patent to Carl M. F. Friden, No. 2,229,889, issued January 28, 1941, as modified by the multiplier patents of Friden, Nos. 2,371,752 and 2,399,917 of March 20, 1945, and May 7, 1946, respectively, and other patents not here pertinent. This basic construction, in the preferred form of the present invention, has been modified and improved by the mechanism shown in the Malavazos patent, No. 3,045,907 issued to one of the inventors herein on July 24, 1952, and relating to the "back transfer" of values from either the accumulator, or product register, or the counter, or quotient register, into a storage register or the keyboard. However, the invention is not limited to incorporation in that particular machine as it can be incorporated in, or applied to, other types of calculating machines on the market. It is, therefore, to be understood that the machine shown in the accompanying drawings and described herein is for purposes of exemplification only and that the invention is not limited thereto.

1. General Arrangement

(FIGS. 1, 4 and 14)

It is conventional for calculating machines to comprise a frame, or body portion, A (FIG. 1) upon which is mounted a register carriage B, the latter being ordinarily shiftable in either direction with respect to the body portion A. The body portion A is provided with a cover 49 through which project the various keys, such as the value keys 50 and the ordinal clearing, or "0", keys 61 which constitute the main keyboard; and various control keys, such as the plus bar 51, the subtraction key 52, the "Add", or automatic single cycle, key 53, automatic tabulation control key 55, left shift key 56, right shift key 57, division key 58, keyboard clear key 59, and register clear key 60. The machine used for exemplification of the present invention also includes a multiplication mechanism, including multiplier value keys 65 arranged as a separate keyboard 50 on the lower left-hand corner of the machine, as shown in FIG. 1 and as described in the patents to Friden, Nos. 2,371,752 on March 20, 1945, or 2,399,917 of May 7, 1946, and the associated multiplier control keys, such as multiplier key 66, accumulate multiply key 67, or negative multiplier key 68.

The cover 77 of the carriage B contains a plurality of ordinarily arranged windows 70, through which are visible the accumulator, or product register, dials 71, and another series of ordinarily arranged windows 72 through which are visible the counter, or quotient register, dials 73. In the machine with which our invention is preferably associated, the carriage also carries a pair of manually operated clear knobs 74 and 75 for clearing, or zeroizing, the accumulator and counter register, respectively. Preferably also, the carriage will contain a plurality of ordinarily arranged tabulator buttons 76 which control the ordinal position to which the carriage will be automatically shifted in certain operations, some of which will be mentioned hereinafter.

The operating mechanism of the machine is, for the most part, supported upon a main frame which includes a base 80 (FIGS. 5, 6, 8, 12, 15, 17, 18, 26 and 28), right side frame 81 (FIGS. 4 and 8), a left side frame 82 (FIGS. 4 and 14), and a left side auxiliary frame plate

83 (FIGS. 4 and 12). The two side frame plates 81 and 82 are interconnected and braced by a plurality of cross-bars 84, 85, 86 and 87 near the rear of the machine (FIGS. 2 and 4). Similarly, the front portion of the machine is braced by a crossbar 91 (FIG. 4) which extends between the right frame plate 81 and the left side auxiliary frame plate 83. Most of the operating parts are mounted upon this frame, and particularly upon the side frames 81 and 82. To the right of the right side frame 81 is an auxiliary, or right side control, plate 88 (FIG. 5) upon which are mounted most of the control keys and their related mechanisms which are found on the right side of the machine. Similarly, to the left of the left frame plate 82, is an auxiliary, or left side control plate 89 (FIG. 14), and an intermediate plate, or bracket, 90 lying between frame plate 82 and the control plate 89, upon which plates are mounted most of the control keys and control mechanisms related to the multiplying mechanism, as well as some of the parts utilized in the present invention.

It should be mentioned that, for the sake of brevity, many mechanisms which are conventional in machines of this kind, such as the division mechanism, the dividend entry mechanism, and the like, which are not pertinent to the mechanisms of the present invention, are not described herein. Those parts which are conventional and which are indirectly related to the operation of this machine will be described as briefly as possible; while those mechanisms which are directly related to the operation of our invention, will be described more in detail. It will be understood, therefore, that we assume that our invention will be associated with a fully automatic calculating machine which has conventional features, such as those mentioned; but that, for the sake of brevity, we will limit our description of conventional elements to those which directly or indirectly relate to the operation of our machine or those mechanisms which must be modified in their operation in order to provide for the most satisfactory operation of the mechanism of our invention.

2. Keyboard

(FIGS. 2 and 7)

The value keys 50 and "0" keys 61 are arranged in longitudinally extending ordinal rows and in transversely extending value banks, as shown in FIG. 1. The keyboard, in the preferred form of the machine shown in FIG. 2, comprises a subassembly in which the keys are mounted in a keyboard frame 95, comprising top and bottom plates 96 and 97, respectively, side frames 98 and 99 (FIG. 7), a front plate (not shown), and a rear plate 101. This keyboard frame is held together as a rigid subassembly by means of interlocking the side and end plates with the top and bottom plates, the assembly being held together by suitable tie rods 102. In our preferred form of keyboard, as outlined in the patent, No. 3,045,907, previously mentioned, the various control means related to the keyboard, such as the keyboard clearing mechanism and the keyboard locking mechanism, are contained within the keyboard frame 95. Such mechanisms are operated by parts contained in the main frame which engage operating elements of the keyboard mechanisms, but which do not require the connecting of one to the other. It is conventional to secure the keyboard frame 95 in the machine by resting the rear plate 101 thereof upon the cross-member 84 and bolting the front portion to the main frame A as by means of the tie rod 103 (FIG. 7) inserted through apertures in ears extending through the front of the keyboard frame plates 98 and 99, and bolted in the left auxiliary and right side frame plates 83 and 81, respectively.

The value keys 50 comprise a key top, or button, 105 and a key stem 106. The key stems are slidably supported in aligned slots in the top and bottom frame plates 96 and 97, and are biased to a raised position by suitable

springs 107 which surround the upper portion of the key stem and are seated between the top plate 96 and the bottom of the key top. A manually operated, or depressed, key stem 106 is latched in its operative position by a conventional latching means which can comprise a latching slide 108 associated with each order of the keyboard. In the conventional machine shown, the latching slides 108 are provided with a plurality of apertures through which the coordinate key stems extend, the latching slide being biased to a forward position by a suitable spring, such as leaf spring 113. Each key stem is provided with a rearwardly extending cam nose 110, above which is located a latching notch 111. The depression of a key 50 will cause the cam 110 on the key stem to force the latching slide 108 rearwardly against the bias of its spring until the key stem has been depressed sufficiently to cause the notch 111 to register with the latching slide, whereupon the latch snaps to its forward position to hold the key stem depressed. Whenever a latching slide is moved rearwardly by the depression of another key in that order, or by the operation of any of the keyboard clearing means, the slide 108 releases the notch 111, whereupon the key stem is snapped to its raised position by the force of its biasing spring 107.

The lower end of each key stem 106 carries a stud, or pin, 112 which engages a differentially angled cam face 212 of one or the other of a pair of selection, or V-notch, bars 210 and 211, as shown in FIG. 2. It is conventional in the machine with which our invention is embodied, to provide a pair of selection bars 210 and 211, the former serving the lower value keys of that order and the latter the higher value keys. It is obvious that the depression of a value key 50 causes the pin 112 on the lower end of its key stem to engage the corresponding cam face 212 and, due to the differential angularity of the respective cam faces 212, to translate the selection bar 210 or 211 forwardly a differential amount. In view of the fact that the depressed key is latched in its operative, or fully depressed, position, the corresponding selection bar 210 or 211 is latched forwardly in its differential position by the engagement of the pin 112 with a latching notch 213 at the lower end of the cam face, which latching notch closely embraces the pin 112.

3. Keyboard Clearing

(FIGS. 6, 7 and 8)

It is conventional in this art to provide mechanisms for clearing the keyboard by releasing the latching slide 108, either by operation of the ordinal "0" key 61 (which has the cam face 110 to translate the latch rearwardly) or by a mechanism operated by the keyboard clear key 59. Such a mechanism is not pertinent to the present invention and hence will not be described in detail. It will be understood, however, that some suitable keyboard clearing mechanism is provided in the machine of this invention and preferably is of the type disclosed in the patent of Malavazos, No. 3,045,907 already mentioned. Such a full keyboard clearing mechanism includes an arm 123 (FIG. 7) rigidly mounted on a transverse shaft 120. On the interior of the keyboard frame 95, the shaft 120 carries a plurality of arms which are operable, upon rotation of the shaft, to move the various ordinal latches 108 rearwardly against the tension of their respective springs 113. The arm 123 is rocked by movement of a slide 126 which is supported for longitudinal movement in the machine by means of slots 128 in the slide, embracing pins 129 carried by the frame plate 81. The forward end of the slide, or link, 126 is formed to lie immediately adjacent the frame plate 81 and is provided with a square stud 119 which extends through an aperture in the frame plate. The rear end of the link 126 carries a stud 127 which engages a shoulder 124 on the lower end of the arm 123, whereby the rear-

ward movement of link 126 is effective to rock the arm 123 to release the keys of the keyboard.

It is conventional in the Friden machine with which our invention is preferably associated to provide an add key mechanism which is selectively operable to automatically clear the keyboard with each machine operation. The keyboard mechanism per se is not pertinent to the present invention and hence need not be described in detail. However, when a squaring operation is desired and the squaring key of the present invention is depressed, it is necessary to disable the add key mechanism in the event that it should have been set in its operative, or automatic clearing, condition, so that the factor inserted in the keyboard will not be erased by the automatic operation of the add key mechanism. Hence, a very brief description of the add key mechanism will be made, and for this purpose particular reference is made to FIGS. 6 and 8. The square stud 119 is adapted to be engaged by a floating link 150, the forward end of which is provided with an upturned nose 151. Normally, as indicated in this figure, the front end of the link 150 is resiliently held in an elevated position by a tension spring 161, while the rear end of the floating link is mounted on an arm 152. This arm 152 is pivotally mounted on the right side of the frame plate 81 by any suitable means, such as stud 153. The lower end of the arm 152 carries a stud 154 which extends to the left through an aperture in the frame plate and is adapted to be engaged by a hook 155 on the forward end of a long link 156 (FIG. 8), depending upon whether the forward end of the link 156 is in the lowered position shown in FIG. 8, or is elevated thereabove. The position of the front end of the link 156 is determined by the operation of the add key by a mechanism not here pertinent and hence not described. The link is operated immediately before the end of a machine cycle by means of a cam arm 157 to which the link is pivotally mounted. The arm 157 is pivoted on the left side of the frame plate 81 by any suitable means, such as stud 158. The lower end of the arm 157 is engaged, just before the end of a cycle, by a stud 159 carried by a disk 160 on the main drive shaft 255. When the link 156 is in its lowered position, shown in FIG. 8, the link in its cyclic reciprocation will engage the pin 154 and thus pull the floating link 150 (FIG. 6) rearwardly. Such rearward movement of the link 156, so long as its nose 151 is in a position to engage pin 119, causes the translation of link 126 (FIG. 7) and operation of the keyboard clearing mechanism.

It was mentioned above that it is necessary in squaring operations to disable this clearing mechanism, even though the add key mechanism has been set in its automatic clearing condition. This is conventionally accomplished, in the Friden machine with which our invention is preferably associated, by means of an arm 165 that is pivotally mounted on the frame plate 81 by any suitable means, such as stud 166. The forward end of this arm is provided with a laterally extending ear 167 which overlies the tip of nose 151 of floating link 150. The arm 166 is also provided with a tongue 168 which lies between the jaws 169 of a disabling arm 170. This arm is rigidly mounted on the right end of a transversely extending shaft 171, which shaft is rocked by the control keys for those operations which require the automatic disabling of the add key mechanism. Thus, as will be explained hereafter in connection with the squaring key, the depression of the squaring key will rock shaft 171 (clockwise in FIG. 6), and hence rock the disabling arm 165 (counter-clockwise in this figure) to depress the nose 151 of floating link 150 to a point below stud 119.

4. Selection Mechanism

(FIG. 2)

It has been mentioned that the lower end of each key stem 106 carries a transversely extending pin 112. This

pin is adapted to engage a differentially angled cam face 212 formed in one or the other of the selection, or V-notch, bars 210 or 211. It is conventional in the machine with which our invention is shown, to provide a pair of selection bars 210 and 211 for each order of the keyboard, the former serving the lower value keys of that order and the latter the higher value keys. The pair of bars is preferred to a single one in order to avoid excessive angles on the cam faces 212, which are necessary when these faces represent nine different values. Each of the cam faces 212 terminates in a notch, or pocket, 213 which tightly embraces the corresponding pin 212 when the key is depressed to its locked position, so that the slide 210 or 211 is locked in a differential position by the depression of a key. The bars 210 and 211 are supported for longitudinal movement in the machine by a pair of supporting arms 214 (only one of which is shown in the drawings), and are biased to a rearward, inoperative, position by a suitable spring (not shown) conventionally tensioned between each slide and its forward supporting arm 214. It is obvious that the depression of a value key causes the pin 112 on its key stem to engage the corresponding cam face 212, and, due to the differential angularity of the respective cam faces, to translate the selection bar 210 or 211 forwardly a differential amount.

The selection bars 210 differ from those shown in earlier machines in that they serve the "1" to "4" keys, while the other selection bars 211 serve the "5" to "9" keys, inclusive. The present arrangement also differs from conventional selection bars due to the fact that there is a double increment, or double increase in angularity, between the notches cooperating with the "1" and "2" keys, as compared to the others. Thus, there is a double increment of movement of the selection bar 210 between the "1" and the "2" keys, as compared to a single increment between all of the others, for the purposes explained in the Patent No. 3,045,907 above-mentioned.

The selection bars 210 and 211 extend rearwardly (to the right in FIG. 2) and are provided at their rearward extremities with perpendicularly formed yokes 216 and 217, respectively. These yokes engage in annular slots formed in the collars of a pair of selection gears 220 and 221, respectively, the gears being slidably but non-rotatably mounted on a longitudinally extending selection, or "square," shaft 222. The square shaft 222 is journaled in the crossframe members, or crossbars 84, 86 and 87, there being one such square shaft for each order of the keyboard. These selection gears 220 and 221 can be arranged on their square shaft in the conventional manner, but we prefer to arrange them in the same manner as in the patent, No. 3,045,907 mentioned, as shown in FIG. 2. In the preferred form of construction, the gear 221 of the odd numbered orders of the keyboard is placed toward the rear of the front section of the square shaft, immediately in front of the crossbar 86. This gear is transposed forwardly on the square shaft from one to five increments corresponding to values of "5" to "9," inclusive. The gear 220 is placed forwardly thereof, normally lying in a neutral position and transposable forwardly one increment for a value of "1," and then three to five increments for values of "2" to "4," inclusive. In the next higher order, the relative position of the selection gears is reversed, the "1" to "4" gear lying at an intermediate position of its square shaft, while the "5" to "9" gear lies forwardly thereof. All of these gears are moved forwardly differential amounts corresponding to the value of the key depressed, with the exception of the double increment between the "1" and "2" keys heretofore mentioned. Thus, the depression of a value key, by translating one or the other of the selection bars 210 or 211, moves the corresponding selection gear 220 or 221 forwardly on square shaft 222 a differential amount corresponding to the value of the key operated.

The rear end of square shaft 222 carries a digitation control spool 225 (FIG. 2) slidably but nonrotatably mounted thereon. The forward end of the spool carries an addition gear 226 and the rear end carries a subtraction gear 227, the spool and the two gears forming an integral assembly. The two gears 226 and 227 are adapted to register with the ordinarily related accumulator gear 235 when the spool 225 is displaced from its central, or neutral, position shown. The spools 225 are moved in unison to either operative position by means of a gate 228 extending transversely across the machine and lying between the two integral gears 226 and 227. The gate 228 is preferably mounted on a pair of arms 229 which are rigidly secured to a digitation control shaft 230. Normally, the assembly comprising the shaft 230 and gate 228 is held in the intermediate, or neutral, position shown by means of a centralizer conventional in the art, but not shown herein. However, various controls, some of which will be mentioned hereafter, are effective to rock the shaft 230 and consequently displace the digitation control spools 225 forwardly or rearwardly as the operation demands, thereby operatively connecting the accumulator gears 235 to either the plus gears 226 or the minus gears 227, and thus driving the accumulator gear 235 incremental amounts in either sign character direction by means of a differential rotation of the selection gears 220 and 221.

5. *Accumulator Register*
(FIG. 2)

An accumulutor register, containing a series of ordinarily arranged register dials 71, is mounted in the shiftable carriage B. In the machine shown in FIG. 1, the accumulutor register contains twenty such dials 71 for a selection mechanism of ten orders. The various ordinal assemblies in the register comprise the dial 71 and the accumulator gear 235, both of which are mounted upon a common dial shaft 236. Preferably, the dial shaft is journaled in a hollow frame bar 237 which forms one of the major frame members of the carriage B. The differential rotation of the square shaft 222, caused by the longitudinal translation of the selection gears 220 or 221 and the rotation of the corresponding actuators 250 or 251, is, upon rocking of the gate 228 from the neutral position shown, effective to rotate the dials 73 additively or subtractively.

It can be mentioned at this point that the carriage frame B comprises, in addition to the hollow frame bar 237, a front carriage rail 238 (FIG. 2) and a rear carriage bar 239, which also extends longitudinally of the carriage or transversely of the machine. These three members: the front rail 238, the hollow frame bar 237 and the rear bar 239, are tied together into a rigid carriage by means of end pieces 240 (FIG. 5). The carriage is laterally shiftable—the front rail riding on rollers 241 mounted on the crossbar 85, and the rear bar 239 sliding in bearings (not shown) carried by the frame plates 81 and 82.

It can also be mentioned at this point that the register dial 71 can be returned to a "0" position by any suitable clearing, or zeroizing, mechanism. That shown in this embodiment is the one normally found in machines of this type, as illustrated by Patent No. 2,229,889, above-mentioned. This mechanism comprises a mutilated gear 242 mounted on each accumulator dial shaft 236. These mutilated gears are engaged by a clearing rack 243 of conventional construction. Longitudinal movement of the rack engages the mutilated gears and returns the dial assemblies to their "0" position, as is well-known in the art. The means for operating the clearing racks 243 will be described under the heading of "Register Clearing."

It can also be mentioned at this point that there is a tens-transfer mechanism between the various orders of the register, but as this mechanism has no relation to the present invention, it will not be described—reference being made to the above-mentioned patent to Friden No. 2,229,889 for a detailed description of this mechanism.

6. *Actuating Mechanism*
(FIG. 2)

The actuating mechanism of the machine shown is of the well-known Thomas-type, modified slightly as to tooth arrangement as described in the Malavazos patent above-mentioned. This type of actuating mechanism comprises a number of stepped drums 250 and 251 arranged transversely of the machine. These drums are mounted on parallel shafts 252 parallel to the square, or selection gear, shafts 222. It is conventional in the Friden machine which is used to exemplify this invention, to provide one actuator shaft 252 for each pair of square shafts 222, and to mount two drums 250 and 251 on each one of these shafts 252—one of the drums to serve the order to the right of the actuator shaft 252 and the other to serve the order to the left. These actuator drums are provided with differentially stepped teeth, so that forward translation of either of the selection gears 220 or 221 causes that gear to lie in the path of travel of a number of teeth on the associated actuator drum corresponding to the value key 50 depressed. It is conventional in the machine of the Friden patents previously mentioned, to use two identical drums on each drive shaft 252 and to divide each drum so that one portion will serve the "1" to "5" keys and the other the "6" to "9" keys, and conventionally both drums are provided with the "1" to "5" section of the forward part of the drum. In the present invention it is preferred to modify these drums so that one will serve the "1" to "4" keys, with a blank space between the one-tooth segment and the two-tooth segment, as is clearly shown on the right-hand section of drum 250 or the left-hand section of drum 251, the other segments lying closely adjacent each other, as is conventional. This construction is desirable in the back transfer operation described in that patent but is immaterial in the present invention. However, as the present invention is preferably incorporated in a back transfer machine, this feature is mentioned in passing.

40 The actuator shafts 252 are driven through miter gears 253 thereon, each one of which meshes with a corresponding miter gear 254 on the main drive shaft 255, as is best shown in FIG. 4. The main drive shift 255 is given a complete revolution with each machine cycle, thereby rotating the actuators 250 and 251 a complete revolution in each machine cycle, and consequently giving the selection gears 220 or 221 and square shafts 222 increments of rotation depending upon the longitudinal position of the selection gears on their respective square shafts.

50 It can be mentioned that it is conventional in machines of this kind, to provide a Geneva stop for each square shaft 222, so angularly disposed on the square shaft as to positively stop rotation thereof at the termination of the digitation phase of a cycle of operation. It is also customary in these machines to start the ordinal digitation operation of the values differentially, in an inverse order, and to stop digitation of all values in an order, simultaneously. Thus, a single Geneva wheel and Geneva block will afford a positive stopping action of the square shafts 222, and consequently the register dials 71, at the end of each digitation phase. For this purpose it is conventional in machines of this kind to provide the actuator shaft 252 with a Geneva wheel 256 and to provide a Geneva block 257 on each square shaft 222.

65 7. *Drive Mechanism and Clutch*
(FIG. 6)

70 Various mechanisms of the machine, including the actuator shafts 252 just described, are given cycles of operation as required by means of a conventional electric motor, not shown. The armature of the motor is conventionally connected to a short shaft 265 by a conventional flexible coupling, not shown. The shaft 265, as shown in FIG. 6, extends through the frame plate 81

and, at its outer end, carries a small pinion 266 secured thereto. The pinion 266 meshes with a larger idler 267, the latter gear being rotatably mounted on a transverse stub shaft 268. The idler, in turn, meshes with a larger gear 269 which is rotatably mounted on the drive shaft 255. The gear 269 forms the driving side of a conventional clutch 270, the driven plate 271 of which is rigidly secured to the drive shaft 255. The operation of the clutch is controlled by a clutch dog 272 which is pivotally mounted on the clutch plate 271 and is resiliently biased into engagement with a ratchet 273 formed integrally with the driving gear 269. The operation of the clutch dog 272 is controlled by a clutch pawl 274 which is pivotally mounted on the frame plate 81 by any suitable means, such as stud 275. Whenever the clutch pawl 274 is rocked (clockwise in FIG. 6), it releases the clutch dog 272, which is then spring-biased into engagement with the ratchet 273 to cause engagement of the clutch. Preferably, the clutch is provided with a full-cycle control of conventional construction.

In the conventional machine with which our invention is preferably associated, the clutch pawl 274 is operated by a link 280, the rear end of which is pivotally connected to the upper end of the clutch pawl. The forward end of the link is pivotally mounted on the upper end of a two-armed lever 281, which is pivotally mounted on the frame plate by any suitable means, such as stud 282. A long pin 283 is riveted on, or otherwise rigidly secured to, the lower end of the lever 281 and extends through an aperture in the frame plate in order to support the forward end of a long switch control link 284. The rear end of the long link 284 cooperates with a suitable switch, such as a conventional micro-switch, not shown, to control the flow of power to the motor, also not shown. By this construction, the clutch pawl 274 and the switch control link 284 are operated in unison to simultaneously engage the clutch and close the power switch to the motor.

The clutch pawl is resiliently held in its clutch disengaging position shown, and the switch link in its open position, by any suitable means, such as spring 285 tensioned between a stud on the frame plate and an ear on a control link 286. This link 286 is pivotally mounted on the pivot pin 287 which interconnects the clutch link 280 and the switch lever 281 previously mentioned. The forward end of the link 286 is slotted to engage a pin 288 positionable by the "ADD" key mechanism. The "ADD" key mechanism is not pertinent to the present invention, and so will not be described; but it can be mentioned that the link 286 can be lifted by pin 288 in the latter portion of each cycle of operation by this "ADD" key mechanism, and thereby release the clutch pawl 274 and switch link 284. Both the clutch pawl 274 and the switch link 284 can be operated by various mechanisms, such as a pin 289 engaging a notch 290 in the lower edge of the link 286, as is conventional in the machine of the patents above-mentioned. The pin 289 is carried by a slide, not shown, operated by the plus and minus keys 51 or 52; but as this mechanism is not pertinent to the present invention, it will not be described.

8. Counter Register

(FIG. 2)

The carriage B also contains a counter, or quotient register, comprising the dials 73. As shown in FIG. 1, it is conventional to provide a series of ordinally arranged counter dials 73 containing a number of dials approximately half that of the accumulator register—in the machine shown in FIG. 1, eleven such counter dials 73 are utilized as compared to twenty accumulator dials 71. This number of dials is selected to provide one more than the orders of the selection and actuating mechanisms, and one more than the ordinal positions of the carriage B, so as to provide an overflow dial in the event that ten or more cycles of operation are performed with

the carriage in its extreme right-hand position. The counter dials 73 are rigidly mounted on ordinarily arranged and longitudinally extending shafts 306, as shown in FIG. 2. The rear ends of the counter shafts 300 are journaled in bearings in the carriage frame member 237, and the forward ends are journaled in bearings formed in the front carriage rail 238. Each counter dial assembly also includes a feed gear 301 and an integral tens-transfer control plate 302 formed as a spool and rigidly mounted on the shaft 300; and a conventional mutilated clearing gear 308. The clearing gears are engaged by a clearing rack 309, which may be of the conventional style disclosed in the Friden patents previously mentioned, so that longitudinal translation of the rack returns all the counter dials to "0."

A counter actuator 303 is mounted on a shaft 304, which shaft is given an oscillatory, or rocking, motion in a plane perpendicular to the axis of the shaft 304 and also a longitudinal translation parallel to the axis of 20 the shaft, with each cycle of operation. Thus, in each cycle of operation, a counting finger 305 of the actuator 303 of the lowest, or units, order of the actuating mechanism, will mesh with the ordinally aligned gear 301 and then be translated in one direction or the other to give 25 the gear a single increment of motion, and thus enter a count of "1" into the dial 73 aligned with the units order of the actuating mechanism. The operation of the counter actuator and its ability to effect the necessary tens-transfer has been described in the Friden Patent No. 3,229,889, and others—and hence no further description 30 of its action is necessary.

It is conventional in the machine with which the present invention is preferably associated, to provide means for operating the counter additively or subtractively, and to 35 control that setting to assign character to be either identical with, or opposite to, the sign character of registrations in the accumulator register dials 71. As such a mechanism is not pertinent to the present invention, it is believed unnecessary to describe it.

9. Register Clearing

(FIGS. 1, 2, 3, 4 and 12)

The accumulator register dials 71 may be cleared, or returned to their "0" registration positions, by a conventional clearing means which is shown in FIG. 2 and which comprises a mutilated clearing gear 242 on each dial shaft 236. In order to conserve space and make the ordinal spacing as small as possible, these gears are alternately arranged on their respective shafts. Associated with the mutilated gear 242 is a double clearing rack 243 which extends longitudinally of the carriage frame and is slidable therein. The rack can be operated by means of a clearing knob 74 (see FIG. 1) or by power through operation of a power-operated clearing bar 415 (best shown in FIG. 3), the construction and operation 55 of which will be shortly described.

Similarly, the counter dials 73 may be zeroized, or cleared, by a conventional clearing means shown in FIG. 2 and which comprises a mutilated gear 308 rigidly mounted on each of the dial shafts 300. Associated with the mutilated gears 308 is a clearing rack 309 which extends longitudinally in the carriage. Likewise, these clearing gears are alternately staggered on their respective shafts and a double rack is provided to operate them. 60 This rack can be operated by means of a clearing knob 75 (FIG. 1) which is attached to the rack, or by power through the clearing bar 415 mentioned in the preceding paragraph.

It will be noted by reference to FIG. 1 that the bar 415 is provided with a pin 416 which is adapted to be engaged by an arm 417 rigidly mounted on the shaft of clearing knob 74. When the arm 417 lies in the clockwise position shown in this figure, it engages the pin 416, whereupon the rightward movement of the clearing bar 75 415 is effective to move the knob 74 and hence the clear-

ing rack 243 to the right to clear the register dials 71. If it is desired to disable the clearing of the register dials 71 upon operation of rack 415, this is readily done by the operator rotating knob 74 counter-clockwise to rotate arm 417 out of the path of travel of the pin 416. The right-hand end of the clearing bar 415 carries a bracket member 418, upon the forward extremity of which is mounted a stud 419 similar to the stud 416 previously mentioned. This stud is adapted to be engaged by an arm 420 rigidly mounted on the shaft of the counter clearing knob 75. When the knob is in the clockwise position shown in FIG. 1, the arm 420 engages the pin 419, so that movement of the clearing bar 415 likewise translates the clearing knob 75 to the right and hence clears the counter register. The clearing of this register can also be disabled by rocking the clear knob 75 counter-clockwise.

The clearing bar 415 is adapted to be driven to the right by a power mechanism which is shown particularly in FIGS. 3 and 4. It should be noted that the bar 415 is mounted on the carriage frame bar 237 by suitable pin-and-slot connections comprising the pins 421 on the rear side of the frame bar engaging slots 422 in the clearing bar 415. The clearing bar 415 is resiliently biased to the left (to the right in FIG. 3) by any suitable means, such as a spring (not shown) tensioned between one of the pins 421 and a corresponding stud on the clearing bar.

In the preferred form of clearing mechanism utilized in the machine with which our invention is associated, the left actuator shaft 252 is extended to the adjacent rear frame crossbar 87 (as shown in FIG. 4) and carries adjacent its rear end a conventional driving clutch member 430. This clutch member carries a driving tongue 431 pivotally mounted thereon, which, when rocked rearwardly, engages a notch in a driven plate 432. The position of the driving tongue 431 is controlled by a conventional control member 433 mounted on the rear end of a clutch control bar 434. The control bar, or pusher rod, 434 reciprocates in cross plates 84 and 86 and is resiliently biased toward the front of the machine by a suitable compression spring 435, compressed between the crossbar 84 and a collar on the control rod, as shown. The control rod 434 can be moved rearwardly against the force of its spring 435 to rock the driver tongue 431 into engagement with the notch in the driven plate 432 to place the clutch in engaged, or driving, position by a pusher link 436. The rear end of the pusher link 436 is provided with a shoulder, shown in FIG. 12, that engages the front end of the clutch control bar 434, and the front end is pivotally mounted on an arm 437 rotatably mounted on a shaft 511. A link 429 is supported at its rear end on a pin 428 which interconnects pusher 436 with arm 437, and at its front end is pivotally connected to an arm 427 which is rigidly mounted on a shaft 438. The shaft 438 is rocked (clockwise if viewed from the right as in FIG. 12) from the operation of the power-operated automatic shift and clear mechanism which will be described hereafter in Section 11; and when so rocked, the rocking of arm 427 and the translation of pusher links 429 and 436 translates the control bar 434 rearwardly to place the clutch in operative position.

The driven clutch disk 432 is mounted on the forward end of a shaft 441 (FIG. 4) which is journaled in the rear cross plate 87 and a supporting bracket 442 which is mounted thereon by suitable spacing studs 443. This shaft 441 carries a clearing cam 444 (also shown in FIG. 3) pinned on, or otherwise rigidly secured to, the shaft intermediate the cross plate and the bracket. Cooperating with the cam is a cam follower arm 445, which, in this instance, is formed as a bellcrank pivoted on a pivot stud 446 mounted on the bracket 442. This follower arm 445 carries a follower roller 447 which engages the periphery of the clearing cam 444, the arm and roller being biased into engagement with the cam by any suitable means, such as spring 448. The actuator

shafts 252 of a Thomas-type machine conventionally rotate in a clockwise direction when viewed from the rear, as in FIG. 3, for in this type of machine, the main drive shaft 255 rotates in one direction only. It follows that the shaft 441 and clear cam 444 will likewise rotate in a clockwise direction, and that the shape of the cam provides a gradual rise from the full-cycle position to about 270°, with an almost instantaneous drop in the final portion of the cycle. Thus, the follower arm 445 is pushed to the right (to the left in FIG. 3) for three-fourths of a cycle of operation and then is released to be snapped back to its full-cycle position by the spring 448.

The upper end of the follower arm 445 is pivotally connected to a rightwardly extending link 449 (leftwardly extending in FIG. 3, which is a rear view), which link is provided with an elongated slot 450 shaped as shown in FIG. 3. This slot embraces a pin 451 mounted on the rear cross plate 87. It is obvious that the rocking movement of the follower arm 445 (to the left in FIG. 3), moves the link 449 in the same direction—the movement of the link being first in a diagonal direction to lift the right end of the link in the first portion of movement and then to give a lineal translation to the right. The upper end of the link is provided with an ear 452 adapted to engage shoulders 453 ordinarily spaced on the lower edge of the clearing bar 415, so that the ear 452 can engage the clearing bar 415 in any ordinal position of the carriage B, and hence clear the registers in any ordinal position.

The clearing, or resetting, operation is limited to the first machine cycle, even though the shaft 438 is held in a rocked position throughout a program, or series, of operations. This is readily accomplished. The pusher rod 436 carries a rightwardly extending pin 454 (as shown in FIGS. 4 and 12), the pin lying forwardly of a shaft 1427 when the clutch rod 43 is in its forward, inoperative position. The shaft 1427, as shown in FIG. 4, is geared to a vertical shaft 1429 by means of miter gears 1430 and 1431, and shaft 1429 is geared to the main drive shaft by means of miter gears 1426 and 1428, whereby the shaft 1427 rotates synchronously with the main drive shaft 255. The shaft 1427 (as shown in FIGS. 4 and 12) carries an eccentric cam 455, which, at approximately the halfway point of a cycle of operation, engages the pin 454 when the pusher rod 436 has been moved rearwardly to push the shift control rod 434 to its operative, or clutch-engaging, position. Upon such engagement of the pin by the cam, the pusher link is lifted from engagement with the clutch control rod 434, whereupon the latter is snapped forwardly by its compression spring 435. Thereafter, the cam releases the pin and permits the pusher link to drop under the force of its spring 456 toward its rod-engaging position. However, the rod will have moved forwardly in the interim, so that the lower edge of the link will ride upon the top of the rod, and thus the rearward position of the pusher link will have no effect on the clear clutch or its control rod. The clutch control rod is, therefore, positively disengaged at approximately the midway point of a clearing cycle and cannot become re-engaged until the shaft 438 is rocked backwardly to its original position to enable the shoulder on the pusher link to engage the forward end of the clutch control bar 434. By this means, in any programmed operation, the clear clutch may be operated once, but only once, during the program.

10. Carriage Shift

(FIGS. 2, 3 and 4)

It has previously been mentioned that the carriage B is shiftable in either direction with respect to the frame, or body, A of the machine. The carriage is shiftable by power under the control of the manually operated keys 56 and 57 (FIG. 1), and also in certain automatic opera-

tions, some of which will hereinafter be described. The mechanism for shifting the carriage is shown particularly in FIGS. 2, 3 and 4, and is essentially that shown and described in the patent to Carl M. Friden et al., No. 2,380,642, issued on July 31, 1945, as modified by the clutch mechanism shown in the patent to Matthew, No. 2,679,916, issued on June 1, 1954.

The movement of the carriage is controlled by a left shift clutch 460 and a right shift clutch 461 (see FIG. 4) of conventional construction, which preferably are mounted on the two rightmost actuator shafts 252. In the machine shown in this embodiment, it is conventional for these actuator shafts to be driven with each cycle of operation so that they rotate in every cycle of every machine operation, but the shifting mechanism is normally disengaged from the actuator shafts. The operation of the left shift clutch 460, from its normally inoperative to its operative position, is controlled by movement of a shift rod 462, resiliently urged toward the front of the machine by a suitable compression spring 463 seated between the crossframe 84 and a collar on the front end of the rod. The rear end of the clutch control rod 462 is provided with a clutch control member 464 which positions the clutch member 460 in its operative or inoperative position, depending upon the position of the control rod 462. Cooperating with the clutch member 460 is a driven member 465 having a notch in which the tongue of the driven member 460 may be engaged. This disk is mounted on a shaft 466 journaled in the rear frame plate 87 and a bracket 467 attached thereto by suitable spacing studs, as shown. This shaft carries a gear 468 which meshes with the larger gear of a compound gear assembly 469, the smaller section of the assembly meshing with a shift gear 470 which is rigidly pinned to, or otherwise mounted on, a shift shaft 471 (see FIG. 3).

Similarly, the right shift clutch 461 is under the control of a right shift rod 474 carrying a clutch control member 475 and similarly biased toward the front of the machine by a compression spring 476. Rearward movement of the rod 474 and control member 475 rocks the tongue of the clutch member 461 into engagement with a notch in a clutch-driven member 477. This member is mounted on a shaft 478 (FIG. 3), likewise journaled in cross plate 87 and the bracket 467, which shaft carries a gear 479 located on the rear end of the shaft adjacent the bracket 467. This gear meshes with a wide idler 480, which also is in mesh with the large gear of the compound gear 469. A full and complete description of these clutches and associated mechanisms is given in the patents to Matthew, Nos. 2,636,678 and 2,679,916, issued on April 28, 1953, and June 1, 1954, respectively.

Rearward movement of the clutch control rod 462 or 474 operates the shift clutch 460 or 461, respectively, to connect an actuator shaft 252 to the shifting mechanism, which includes the driven plates and gear trains just mentioned. It is obvious that operation of either of the rods will selectively drive the shift gear 470 in opposite directions, depending on which clutch is operated. The shaft 471, upon which the shift gear 470 is rigidly mounted, also carries a shift plate 484 which is provided with four equally spaced pins 485. These pins are adapted to engage in notches 486 of the conventional shift rack 487 mounted on the rear side of the carriage frame bar 237. In this manner, the rearward movement of left shift rod 462 causes the carriage B to be shifted to the left, while movement of the right shift rod 474 causes the carriage to be shifted to the right.

The left shift rod 462 and right shift rod 474 can be operated from the shift keys 56 and 57, respectively, by conventional mechanisms which are not pertinent to this invention and which, therefore, will not be described. In addition, the left shift control rod 462 will be operated by the automatic clearing and shifting mechanism de-

scribed in the next section, and the right shift control rod will be operated at the end of each ordinal series of a multiplying operation, as described in section 12 dealing with multiplication operations.

The terminal notch 486 on the right end of the shift rack 487 (at the left side of FIG. 3), is formed by an override pawl 500 pivoted on the rack by any suitable means, such as by stud 501. The pawl is resiliently biased into alignment with the notches by any suitable means, such as spring 499 which is conventional in this type of mechanism, in which position a notch formed in the pawl constitutes the terminal notch of the rack. The lower edge of the pawl is provided with a cam face adapted to be engaged by one of the rotating pins 485 when the drive plate 484 attempts to move the carriage to the left beyond the extreme left-hand position, thereby rocking the override pawl on its pivot 501 (counter-clockwise when viewed from the rear as in FIG. 3). The outer, or right-hand, end of the pawl 500 is formed as a nose 502, which, in the extreme left-hand position of the carriage, overlies an ear 503 of a vertical slide 504 mounted on the rear side of the cross plate 87 by suitable pin-and-slot connections, such as constituted by screws 505 threaded into the cross plate 87, embraced by slots 506 in the slide member. The slide 504 is resiliently biased to its upper position by any suitable means, such as a spring (not shown). The lower end of the slide overlies a horizontal arm of a bellcrank 508 (see also FIG. 4) which is pivotally mounted on any suitable means, such as the digitation control shaft 230. The vertical arm of the bellcrank is connected to a forwardly extending link 509, as shown in FIG. 4, which link is connected at its forward end to the upstanding arm of a transverse bail 510. The bail 510 is pivotally mounted on a transverse shaft 511 and its left-hand leg 512 extends rearwardly and upwardly to engage a pusher link operated by the automatic left shifting mechanism in order to disable the same when the carriage B reaches the extreme left-hand position.

11. Automatic Clearing and Shifting

(FIGS. 4, 6, 8, 10 and 11)

In the Friden calculating machine with which the present invention is preferably associated, multiplication is always initiated with the carriage in an extreme left-hand position. In some operations the carriage is automatically cleared; while in others, such as negative multiplication or accumulative multiplication, the register is not cleared even though the carriage is shifted to the extreme left-hand position. The mechanism for so shifting the carriage and clearing the registers, if that type of operation is selected by the operator, is described in detail in the patent to Machado No. 2,650,761. In view of this patent it is believed that a complete and detailed description of this mechanism is not necessary, but it will be very briefly mentioned because it is preferred to use it in connection with multiplication controlled by the present invention.

This mechanism is operated by the rocking of the shaft 438. This shaft extends entirely across the machine, its right end being journaled in the right side frame plate 81 (FIG. 4) and its left end in the left side control plate 89 (FIG. 17). Adjacent its right end (preferably immediately to the left of the right-hand control plate 81, as shown in FIGS. 4, 6 and 8), the shaft 438 carries a V-shaped lever 1435, the forward extending arm of which plays no part in the present invention. The vertical arm of this lever carries a roller stud 1436 which engages the forwardly extending arm of a three-armed lever 1437, which is rotatably mounted on any suitable means, such as the shaft 511 already mentioned. The rearwardly extending arm of this lever terminates in a hook 1438 which lies behind the pin 283 that connects the switch control link 284 to the clutch lever 281 already

described. Hence, the rocking of the shaft 438 (clockwise in FIG. 6, or counter-clockwise in FIG. 8), through the rocking of levers 1435 and 1437, causes the engagement of the clutch and the closing of the motor switch, and thus initiates machine operation. The shaft 438 is held in a rocked condition by the control keys which control the rocking of this shaft until the operation is completed, so that the machine will continue to cycle until the termination of the operation, which, in this case, is multiplication.

A third arm of the lever 1437 extends upwardly from the shaft 511 and carries a roller 1439 which engages the rear edge of an extension of an add key disengaging lever 1440. This lever is rotatably mounted on the frame plate 81 by any suitable means, such as pivot stud 1441, and at its forward end carries a pin 1442 which extends to the right through an aperture in the frame plate, as best shown in FIG. 6. This pin, in turn, underlies the rear end of a two-armed lever 1443, which preferably is pivoted on the stud 153 adjacent the arm 152. The forward arm of this lever 1443 is formed as a nose 1444 which overlies an ear 162 on the floating link 150 that operates the keyboard clearing mechanism. Thus, the rocking of the lever 1437 (counter-clockwise in FIG. 6) rocks the lever 1440 to lift the rear end of the lever 1443 (rocks it counterclockwise in FIG. 6) to disable the clearing link 150. Thus, the rocking of shaft 438 not only initiates machine operation but disables the add key mechanism, if that mechanism happens to have been set to an operative position.

At an intermediate location, the shaft 438 carries an L-shaped lever 1448 (FIGS. 4, 10 and 11) which is pinned to, or otherwise rigidly mounted on, the shaft. The upper end of the vertical arm of this lever carries a pin 1449 engaging a slot 1450 in a link 1451. A spring 1452 holds the link and arm in the retracted position shown in FIGS. 10 and 11. The rear end of the link 1451 is connected to one leg of an eccentrically mounted bell-crank 1453 that is mounted on an eccentric carried by the shaft 1427 which rotates synchronously with the main drive shaft 255. The other arm of this bellcrank is shaped as a hook member 1454 adapted to engage a pin 1455 mounted on the upper end of an arm 1456. It will be understood that the bellcrank 1453 reciprocates constantly, for the shaft 1427 rotates synchronously with the drive shaft 255 to which it is geared. However, in the normal angular position of the bellcrank shown in FIG. 10, the hook reciprocates by, but does not engage, the pin 1455, so that such operation of the bellcrank is an idle one. However, as soon as the bellcrank is rocked by its link 1451, the hook 1454 will engage the pin 1455 at the outer extremity of its stroke and will then rock the arm 1456 (counter-clockwise in FIG. 10 or clockwise in FIG. 11) to an operative position. The arm 1456 is rigidly mounted on the shaft 511 and, when rocked to its extreme position, a pin 1458 on the lower end thereof engages the latching shoulder of a latch arm 1459, thereby latching the arm 1456 and shaft 511 in the operative position. It can be noted here that the latch is disabled when the shaft 438, and the lever 1448 pinned thereon, are returned to their original angular position shown in this figure.

The shaft 511 also carries an arm 1465 (FIGS. 4 and 10) rigidly mounted thereon, which arm supports the forward end of a pusher link 1466. A spring 1467 biases the shaft 511 to its inoperative position and the pusher link 1466 to its lower position shown. The rear end of the pusher link 1466 has a shoulder adapted to engage a pin 1468 carried by an arm 1469 which is formed on the left end of a sleeve 1470 (see FIG. 4). The sleeve 1470 is rockably mounted on a shaft 1471 journalled in the right frame plate 81 and in a bracket 1472 mounted on the crossbar 84. The right end of the sleeve (as shown in FIG. 4) terminates adjacent the

left shift clutch control rod 462 and, at its right end, carries an arm 1473 rigidly secured thereto. This arm carries a long rightwardly extending pin 1474 which engages the front end of the control rod 462, so that the rocking of shaft 511 by the engagement of the eccentrically mounted hook 1453, 1454 with the pin 1455 on arm 1456, rocks the sleeve 1470 to push the left shift control rod 462 rearwardly and thereby engage the left shift clutch.

10 The pusher link 1466 which controls this automatic left shift operation, overlies the rearwardly extending left leg 512 of the bail 510, as shown in FIGS. 4 and 10. Hence the operation of the override pawl and its connected mechanism, and the consequent rocking of bail 510, when the carriage B reaches its extreme left-hand position, is effective to lift the pusher link 1466, so that the shoulder no longer engages the pin 1468. Thereupon the pusher rod spring 463 snaps that rod forwardly to an inoperative position and a spring 1475 (FIG. 10), tensioned between the lower end of the arm 1469, snaps that arm to its normal inoperative position, whereupon the lower edge of the pusher link 1466 rides upon the pin 1468 and has no further control of a left shifting operation.

25 It has already been explained (in Section 9) that the rocking of shaft 438, simultaneous with the energizing of the motor and the engagement of the drive clutch, engages the clear clutch 430, 432 (FIG. 4), so that in the first cycle of operation the registers in the carriage 30 will be cleared. It is in this cycle that the eccentrically mounted hook 1453 will engage the pin 1455 to rock the arm 1456 and shaft 511 to cause the engagement of the shifting clutch. The machine with which the present invention is preferably associated, as well as 35 other commercial machines on the market, has interlocks which prevent the engagement of the clutch until the end of the current cycle and thus prevents simultaneous operation of the clearing mechanism and the shifting mechanism, i.e., the registers are cleared in the 40 first cycle of operation, but the shifting of the carriage to the home, or extreme left-hand, position does not begin until the second cycle of operation. If the carriage happens to be in the home position at the start of a multiplication operation, the override pawl and 45 its associated mechanism will be operated about half-way through that second cycle.

12. Conventional Multiplication Mechanism (FIGS. 1, 12, 15, 17 and 18)

50 Preferably our invention is embodied in a conventional Friden machine provided with a multiplication mechanism of the type described in the patents to Friden, Nos. 2,371,752 of March 20, 1945, and 2,399,917 of May 7, 1946. It will be understood by those skilled 55 in the art that our invention could be used in substitution for the multiplying mechanisms of these last two mentioned patents. However, the mechanism of the present invention is designed primarily to use a value "back transferred" from the accumulator or counter registers as a multiplier factor, and we believe that 60 the machine has greater flexibility if it is used in conjunction with the conventional multiplier mechanism of the Friden patents just mentioned. The present mechanism has, therefore, been designed to cooperate with the conventional multiplier mechanism and use many of the controls and operating mechanisms of that type of machine. For example, we propose the use of the conventional multiply control keys 66, 67 and 68 of that 65 machine for controlling like operations when using the value standing in the storage register dial 701 as a multiplier. When the machine is set for such storage dial multiplication, it is necessary to disable the control of the multiplying operation by the conventional multiplier segments and disable the convention multiplier pin 70 carriage shift, as well as to enable new control mech-

anisms. However, we propose to initiate both types of multiplication operations with the conventional three multiplier keys: the multiply key 66 (which clears the accumulator register dials 71 as a preliminary step to the multiplication operation); the accumulator multiply key 67 (which does not clear the register either before or after the operation); and the negative multiply key 68 (which operates the actuating mechanism subtractively in order to subtract one product from another).

In view of the preferred use of the conventional control and operating mechanisms, these will be explained in sufficient detail to enable a clear understanding of the preferred form of our invention. However, it is believed unnecessary to explain the operation of the conventional multiplier storage segments, except to briefly mention that the values are inserted into this mechanism by operation of the multiplier value keys 65. These keys are effective, by means of mechanism not here pertinent and therefore not shown or described, to differentially set the conventional multiplier segments 315 (FIGS. 15 and 18). The subsequent depression of one of the multiplier control keys 66, 67 or 68 initiates a machine operation which involves the restoration of the multiplier segment 315 in the operative position step-by-step to "0" by means of counting pawl 316. When the segment in the operative position returns to "0," the upper edge thereof engages an ear 319 on the front end of a shift control arm 317 (FIG. 17) to rock it (counterclockwise in this figure). In the prior machines, this shift actuating arm 317 was a two-armed lever pivoted on a shaft 318. In the present invention it is necessary to modify this member to form it in two components and to lock them together for integral operation in conventional multiplication operations and to disconnect them for multiplication by a factor standing in the storage register dials 701. Thus, in the instant invention the shift initiating member 317 is formed as a bellcrank pivoted at its elbow on shaft 318. The forward end of the horizontal arm of this bellcrank carries the ear 319 which is adapted to be engaged by the return of a multiplier segment 315 to its "0" position. The other end of the bellcrank carries an ear 320 adapted to engage a notch in an interponent to be described in the following paragraph.

The other section of this shift initiating, or programming, member comprises a second bellcrank 325 (FIGS. 15 and 17), likewise pivoted on shaft 318. The forward end of this second member is provided with a nose 326 adapted to engage shaft 576 at the end of the rocking of the members (clockwise in these figures) and hence prevent overthrow of the two sections. The two sections of this programming device are interconnected by means of an interponent, or link, 327 which is pivotally mounted on the second member 325 by any suitable means, such as stud 328. The interponent is provided with a notch 329 adapted to engage the ear 320 of the first section 317. Preferably, a shoulder 330 is provided on the interponent 327, behind the notch 329, in order to prevent over-rocking of the two sections of the programming member. This interponent is also provided with a downwardly extending tail 331 which is adapted to be engaged by a pin 1018 on the upper end of a rocking lever 1014 which is rocked (counter-clockwise from the position shown in FIG. 17) upon conditioning the machine for the multiplication operation of the present invention. The two sections 317 and 325 of the programming member are resiliently held in a retracted position by a spring 332, and the interponent 327 is resiliently biased toward a latching position with member 317 by a second spring 333.

Normally, the programming member is held in the disabled position (shown in FIG. 17) by means of a link 338, the lower end of which is pivoted on the rear end of a rocker arm 339. The upper end of this link is provided with a notch 340 engaging the stud 328, while the lower end is provided with a slot 341 which engages the pin 342 by means of which the link and arm 339 are piv-

totally connected. A spring 343 provides a yieldable connection between these two members, and biases the link to the retracted position shown in this figure. The rocker arm 339 is pivotally mounted on the control plate 89 by some suitable means, such as pivot stud 349; and connected to a spring-powered multiplier operating arm 344 by a suitable pin-and-slot connection, such as a pin 345 on arm 344 engaging a slot 346 on arm 339. The operating arm 344 is pivotally mounted on the frame plate 89 by any suitable means, such as a stud 347, and is strongly biased to an operative position by a relatively strong spring 348.

This operating arm 344 is normally latched in the inoperative position shown by two latches: a latching arm 354 which is operated by the override pawl, as will hereinafter be explained, and a latching arm 355 which is operated by one of the multiplier control keys 66, 67 or 68. Both of these latches engage a control arm 356 which is pivoted on the control plate 89 by any suitable means, such as stud 357. This arm carries a pin 358 at its rear end, which is embraced within a slot 359 formed in the front end of the operating arm 344. Thus, the control lever 356 is latched in an inoperative position by the two latches mentioned; and the control lever, in turn, holds the operating arm 344 inoperative until both of the latches have been operated. Whenever both latches are operated (one latch by depression of a multiplier control key and the other by the operation of the override mechanism when the carriage reaches its extreme left-hand position), the operating arm rocks from the bias of its strong spring 348 (counter-clockwise in FIG. 17) to rock arm 339 and translate link 338 upwardly under the bias of spring 343. The operating arm 344 remains in this operative position until the multiplication operation is terminated, but the link 338, because of slot 341 and the resiliency of spring 343, can permit operation of shift control arms 317, 325 whenever the operative multiplier segment 315 returns to its "0" position. Such return to the "0" position rocks the control assembly 317, 325 to terminate the multiplication operation in one order, shift the carriage B, and reinitiate operation in the next order.

It can be noted here that the rocking of the two arms 344 and 356 is effective to initiate the multiplication operation by lifting link 360 which controls the operation of the feed pawl 316—this link being pivotally mounted on the pin 358 which interconnects the two levers. Also, the rear end of the arm 356 is formed as a bracket which carries a pin 361 engaging the lower end of a lever 362. This lever is pivotally mounted on a stud 363 carried by a bracket of the control plate. The upper end of the lever 362 bears against the left-hand face of a cam 364 which is slidably but nonrotatably mounted on the drive shaft 255. Normally this cam is biased to a left-hand position by a spring (not identified) which embraces the drive shaft 255 and is seated between the cam 364 and a second cam 365 (FIG. 14) which is pinned to the drive shaft but which is not pertinent to the present invention. Thus, the rocking of the levers 356, 344 rocks lever 362, which cams the cam 364 to the right to an operative position. All of these mentioned parts are held in that position throughout the multiplication operation, i.e., until the multiplication control key is released and the operating mechanism is restored to its initial inactive position.

It is conventional, in the machine with which our invention is preferably associated, to terminate the repeated addition or subtractive operations in one order of the register and to shift the carriage to the next ordinal position whenever one of the multiplier segments 315 returns to its "0" position. This is secured by the end of the segment engaging ear 319 (FIG. 17) and rocking the shift control lever 317 (counter-clockwise in this figure). In the present invention this operation rocks the member 325 in the same direction, and in conventional multiplication, this second member 325 operates as the second arm 75 of the lever 317. In our invention, as in the previous

machines, the means for terminating the ordinal operation in the operative order, shifting the carriage and the multiplier pin carriage, and reinitiating operation in the adjacent higher order, is controlled by the rocking of the member 325 (counter-clockwise in FIG. 17), as will now be described.

A link 370 (FIG. 15) is suspended from the arm 325 by any suitable means, such as a pivot stud 371. The lower end of this link is pivotally connected to a second link 372 by a suitable pivotal connection, such as stud 373. The forward end of this link is pivotally connected to an arm 374 which is pivotally mounted on a shift control shaft 375. The rear end of the second link 372 is provided with a hook-shaped nose 376 which engages an ear 377 on a latching member 378. The latch member 378 is pivoted on a convenient shaft 379, and is provided with a shoulder 380 that underlies an offset portion of a control arm 381. The arm 381 is pinned on, or otherwise rigidly secured to, the shaft 375. A restoring arm 382 is also pinned on, or otherwise rigidly secured to, the shaft 375 and is biased to a rearward position (counter-clockwise in FIG. 15) by a relatively strong spring 383. Thus, when the latch 378 releases the arm 381, that arm, shaft 375 and arm 382 are pulled rearwardly (counter-clockwise in FIG. 15) by the spring 383. Both of the arms 374 and 382 are adapted to be engaged by a roller 384 on the cam 364, the arm 374 being oscillated in each cycle of the multiplication operation and the arm 382 being latched at the extremity of its throw. Normally the link 372 lies in a position above the ear 377 (above the position shown in FIG. 15). However, when the control lever 317, 325 is rocked (counter-clockwise in FIG. 15) by the return of the operative segment to "0" position, the link 370, and consequently link 372, are lowered into the position shown in FIG. 15 at about the midpoint of that cycle of operation. Thereafter, the roller 384 engages the arm 374, as it does in all cycles of operation, and rocks it forwardly (clockwise in FIG. 15) and pulls the link forwardly with it. When the rear end of the link 372 is lowered by the rocking of the control lever 317, 325, the hook 376 engages the ear 377 of latch 378 and thereby pulls the latch forwardly to unlatch the arm 381.

The rocking of shaft 375 and arm 382, which follows immediately, disables the conventional segment restore pawl 316 by means of link 385 and arm 386, the latter being pinned on, or otherwise rigidly secured to, a short transverse shaft 387. The particular mechanism by means of which the pawl 316 is disabled is not pertinent here, but includes the check pawl 321 (FIG. 18) on the right end of shaft 387, and when rocked, disables pawl 316. The rocking of shaft 375 conventionally enables a shift of the multiplier pin carriage (which carries the ordinarily arranged segments 315) by means of an arm 388 (FIG. 19). In the conventional machine of the Friden patents, Nos. 2,371,752 and 2,399,917, previously mentioned, this arm is pinned to the shaft 375. As this shift arm must be disabled in the present invention, it is pivotally mounted on the shaft 375 and is yieldably operated from the rocking of the shaft by means of an arm 389 which is pinned to the shaft adjacent the arm 388. This arm is connected to an interponent 390 by means of a spring 391, the spring being tensioned between a pin 392 on arm 389 and a pin 393 on the interponent 390. A tail of the interponent engages a pin 394 on arm 388, whereby the rocking of shaft 375 and arm 389 resiliently lifts the arm 388 to lift the conventional feed pawl into feeding alignment with the multiplier segment carriage. However, when multiplication is being controlled from the storage dials 701, rocking of the interponent 390 can be blocked by means which will be described in Section II-E, Subsection 4(b).

The rocking of shaft 375 is also effective to initiate a right shift of the carriage B by a mechanism best shown in FIGS. 4 and 11. As shown in FIG. 4, the shaft 375

extends to, and is journalled in, the right frame plate 81. Adjacent the right shift control rod 474, this shaft carries an arm 396 which is pinned to, or otherwise rigidly secured on, the shaft. The outer end of this arm carries a long pin 397 extending to the right, which pin lies within a slot 398 formed in an arm 399 that is slidably and rotatably mounted on the shaft 375. This arm is resiliently biased to the left from the position shown in FIG. 4 by a compression spring 400 which embraces the shaft 375 and is seated between the bearing in the right frame plate 81 and the arm. A bail 401 extends to the left from the arm 399, the left end of which bears against the right end plate of the multiplier carriage frame, as is conventional although not shown herein. So long as the multiplier carriage is in its home position, the arm 399 is ineffective; but as soon as the carriage is escaped to the left by the insertion of multiplier values into it, the arm 399 is likewise permitted to escape to the left. In its leftmost position, the upper end of the arm 399 engages a pin 402 carried by an arm 403 that is rotatably mounted on the shaft 1471. This pin bears against the front end of the right shift control rod 474, as best shown in FIG. 11. In the conventional machine, this pin 402 terminates at a point to the right of, and immediately adjacent the control rod 474. However, in the present invention, the pin is offset, as at 404 (FIG. 4), to the rear in the plane of the arm 399 a distance sufficient to enable rocking of the arm 399 without engaging the pin 402 or the offset portion 404. Further to the right of the offset portion, the pin is again offset in a reverse direction, so that the outer end 405 is coaxially aligned with the pin 402. Hence the arm 399, if shifted to the right from the position shown in FIG. 4, will engage the section 405 and thereby rock the pin to force the right shift control rod 474 rearwardly to its right shift position. It will be understood that in the multiplication operation of the present invention, which will take place under the control of the value standing in the storage register dial 701, a carriage shift must be effected regardless of the position of the conventional multiplier carriage. Therefore, the arm 399 must be effective to engage the pin 402, 405 either when a value stands in the multiplier carriage (and the arm 399 shifts to the left), or when it is desired to use the value in the storage dials as a multiplier value (and the arm 399 is shifted to the right), but must not be effective in the normal condition of the arm. Means will be described in connection with the description of the storage dial multiplier mechanism to describe the shifting of the arm 399 to the right to a position in opposition to the outer end 405 of the pin 402. It follows that when the shaft 375 is rocked in a multiplication operation, the rocking of arm 399 causes the operation of the right shift controlling rod 474 to effect a one-order shift of the register carriage B to the right.

It has been mentioned that the three multiplier control keys initiate three types of operation: "MULT" key 66 initiating a clearing of the registers followed by multiplication; the "ACCU MULT" key 67 initiating a multiplication operation by repeated addition without preliminary clearing; and the "NEG MULT" key 68 initiating a repeated subtractive operation without first clearing the accumulator register dials 71. The means for so controlling the operation of the machine will now be described.

It is seen by reference to FIG. 12 that the stem of the "MULT" key 66 carries a pin 520 embraced in a slot 521 in the forward end of a control arm 522. The control arm 522 is pinned on the auxiliary left side frame plate 83 by any suitable means, such as pivot stud 523, and carries a pin 524 on a lower projection of the arm. This pin abuts against the forward edge of the arm 427 which is pinned on, or otherwise rigidly secured to, the initiating shaft 438. Hence, depression of the key 66 initiates a machine operation, which first involves clear-

ing of the accumulator register dials, then the shifting of the carriage to the extreme left-hand position.

The pin 520 overlies the lower end of an L-shaped leg 530 of a bail 531 which is pivotally mounted on a cross shaft 532. An intermediate leg 529 (FIG. 17) of the bail 531 is extended downwardly, and at its lower end is pivotally connected to the front end of a longitudinally extending link 533. The rear end of the link 533 is pivotally connected to the lower end of a vertically extending arm of a bellcrank 534 which is mounted on a short shaft 535 journalled in an extension of the left-hand control plate 89. A spring 536 biases the bellcrank 534, link 533 and bail 531 to the inoperative position shown in FIGS. 12 and 17. The forward end of the bellcrank 534 is pinned to a short link 537, the upper end of which is secured to a digitation control arm 538. This arm is pivotally mounted on a stud 539 mounted on the left-hand control plate 89, and is normally biased to a lowered position shown in FIG. 17 by a suitable spring 540, the other end of the spring being connected to an additive control arm 545 (FIG. 15). Thus, the upwardly rocking of the arm 538 (clockwise in FIG. 17) from the depression of the multiplier key 66, resiliently lifts the arm 545 to its operative position. Such movement is blocked, until the proper time in a multiplication operation, by a roller 546 carried on the rearward end of the arm 325. The rearward end of the additive control arm 545 carries a shoulder 547 adapted to engage a pin 548 secured to the upper end of a digitation control lever 549. This digitation control lever 549 is rigidly secured to the left end of the digitation control shaft 230. Thus, when the additive arm 545 is lifted to cause the shoulder 549 to engage the pin 548 and the arm 545 is thereafter shifted rearwardly, the consequent rocking of shaft 230 will rock the digitation control gate 228 to its additive position. The forward end of the additive link 545 (FIG. 15) is pivotally mounted on the upper end of a bellcrank setting lever 550. The bellcrank 550 is pivotally mounted on a short shaft 551 extending between the left side control plate 89 and the intermediate, or auxiliary, left side frame 90. At its upper end the bellcrank 550 carries a roller 552 which engages the periphery of the cam 364 whenever the cam is shifted to the right, as heretofore explained, the bellcrank being resiliently biased into engagement with the cam by means of tension springs 553 and 554. The cam 364 has a single lobe which, shortly after the start of a cycle (the shaft 255 and hence cam 364 rotating in a counter-clockwise direction in FIG. 15), forces the follower bellcrank 550 rearwardly to thereby set the digitation control shaft 230 to its additive position. The follower bellcrank is latched in its operative position by means of a latch arm 555, the shoulder on the lower end of which engages a stud 557 on the rear leg, or tail, of the bellcrank 550. The latch arm 555 is resiliently biased into latching engagement by means of a spring, not shown, and is released when the operating lever 381 is permitted to drop, as an offset portion of that arm overlies a forwardly extending tail 556 of the latch, as shown in FIG. 15.

By means of the mechanism here described, the depression of the multiplier key 66 resiliently biases the additive setting arm 545 to operative position. Then, when the initiating arm 344 is permitted to rock, following the overdraft cycle and the release of both latches 354 and 355 above-mentioned (FIG. 17), and the consequent lifting of link 338 and the rocking of the shift control arm 317, 325 enables the arm to rock (clockwise in FIG. 17) in that override cycle, the bellcrank follower 550 (FIG. 15) is pushed rearwardly to set the digitation control mechanism in its additive position at the start of the following cycle.

The depression of key 66 is also effected to release the second latch 355 which blocks operation of the initiating lever 344 and control lever 356. The left leg 560 of the bail 531 (FIG. 17) extends downwardly

from the pivot shaft 532, and is bent rearwardly as shown in this figure. The rearward end of the leg overlies a pin 561 riveted to, or otherwise affixed on, a U-shaped lever 562 that is pivotally mounted on the shaft 532. The pin 561 overlies the forwardly extending arm 563 of the bellcrank that constitutes the latch 355. This bellcrank is pivotally mounted on the left-hand control plate by any suitable means, such as stud 564. Hence the depression of key 66, by rocking arm 560 and U-lever 562, moves the second latch 355 to release control lever 356 to the sole control of latch 354.

The key 66 is latched in its depressed position, and thereby holds all the mechanisms controlled thereby in their operated position, by conventional means which comprises a shoulder 569 (FIG. 12) on the key stem which cooperates with a latch 570 which is rigidly mounted on a transverse shaft 571 extending between the left-hand control plate 89 and the auxiliary frame plate 83. The shaft and latch are biased to a latching position by means of a conventional spring, not shown. In conventional operation these latches are released by the return of the segment, or multiplier, carriage to its extreme home position, as is explained in the Friden multiplier patents heretofore mentioned.

The accumulate multiply key 67 likewise initiates a positive multiplication but in doing so, disables the automatic clear, so that one product can be added to another. This key has a pin-and-slot connection with a control lever 575 (FIG. 17) that is pivotally mounted on a short shaft 576 extending between the left-hand control plate 89 and the auxiliary, or intermediate, side frame plate 90. The rear end of this lever extends rearwardly, as shown in FIG. 15, and at its rear end is formed with a downwardly turned projection 577. A stud 578 riveted to, or otherwise affixed on, this projection lies within a slot 579 (as shown in FIG. 17) formed adjacent the rear end of the additive digitation control arm 538. Thus, the rocking of the arm 575 by the depression of the accumulate multiply key 67 lifts the rear end of the additive control arm 538 (rocks it clockwise in FIG. 17) and conditions the machine for additive operation in the same manner as the depression of the multiply key 66. Incidentally, the lifting of the additive control arm 538 rocks the bellcrank 534, translates the link 533 and rocks the bail 531 to rock the U-shaped lever 562 and hence rock the latch 355 to its disengaging position. Also this key is latched in a depressed position by means of a latch arm 580 rigidly mounted on the shaft 571, the ear on the latching arm 580 engaging a shoulder formed on the key stem 67.

An operating lever 585 is pivotally mounted on the shaft 576 immediately adjacent the accumulate multiply control arm 575. The forward end of this lever carries a stud 586 which extends to the right under the accumulate multiply lever 575 and the negative multiply lever 606, to be described hereafter. A projection 587 extends downwardly from this lever, the lower edge of the projection engaging a pin, or stud, 588 carried by an arm 589 that is rigidly secured to the left end of the shaft 438. It will be remembered that the shaft 438, when rocked (counter-clockwise in FIG. 17) is effective to engage the main clutch and close the switch that controls the flow of power to the motor, and so initiates a machine operation.

The lever 585 also carries a pin 594, as shown in FIG. 17, which is engaged by the slotted upper end of a link 595. The lower end of the link 595 is pivotally secured to an arm 596 mounted on the left end of a shaft 597. The shaft 597 extends from the left side control plate 89 to the auxiliary frame plate 83, being rotatably journalled in bearings carried by these frame plates. The right end of the shaft 597, as shown in FIG. 12, carries an arm 598 rigidly mounted thereon. The upper, or free, end of this arm carries a pin 599 riveted thereon, which pin overlies a tail portion 600 of a disabling lever 601. The dis-

abling lever extends rearwardly and has a laterally extending ear 602 (see also FIG. 4) which underlies the pusher link 436 that controls operation of the clear clutch control rod 434. Hence, the rocking of the shaft 597 (counter-clockwise in FIG. 17 and clockwise in FIG. 12) rocks the disabling arm 601 (counter-clockwise in FIG. 12) to lift the pusher link 436 upwardly from engagement with the clear control rod 434. Hence, the rearward translation of the pusher link 436, which results from the rocking of shaft 438, is ineffective to clear the registers, but otherwise the operation is the same as that initiated by the multiplier key 66.

The negative multiply key 68 (FIG. 17) has a pin-and-slot connection, such as formed by a pin 610 on the key stem embraced within a slot 612, with a negative, or subtractive, multiply lever 606. The negative multiply lever 606 which lies immediately to the right of the accumulate multiply control lever 575, is likewise pivoted on the shaft 576, and its lower edge also overlies the stud 586 carried by the operating lever 585. The rear end of the negative control lever is shaped substantially like the rear end of the accumulate multiply lever, and is connected by means of a spring, not shown, to a subtractive control link 607 (see FIG. 15). This link is also pivotally mounted on the follower bellcrank 550 and has an upward extension which abuts against the roller 546 carried by arm 325. The lower end of this lever is formed with a latching notch, or shoulder, 608 adapted to engage a pin 609 on the lower end of the digitation control lever 549. Hence, the depression of the negative multiply key 68 rocks the negative control arm 606 (clockwise in FIGS. 17 and 15), thereby resiliently biasing the interponent 607 upwardly so that it will engage the pin 609. Then, as soon as the shift control lever 317, 325 is enabled for operation and cam 364 rocks follower 550, link 607 is moved rearwardly to rock the lever 549 and shaft 230 to a subtractive operating position.

The pin 610, which forms a part of the connection between the key 68 and the negative subtract lever 606, overlies an ear 611 (FIG. 17) that is formed on the upper and rearwardly extending arm of the U-shaped lever 562. Hence, the depression of the key 68 rocks the U-shaped lever 562 directly, thereby disengaging the latch 355 from the ear on the forward end of the control lever 356. Since the negative control arm 606 overlies the pin 586 of the operating lever 585, the depression of the key 68 will also enable machine operation and disable the accumulator register clearing operation, as outlined above in connection with the accumulate multiply key.

It was previously mentioned that there are two latches blocking operation of the initiating levers: latch 354 and latch 355 (FIG. 17). One of these latches, bellcrank latch 355, is rocked to an unblocking position by the depression of each of the multiplier keys 66, 67 and 68, as has been described above. The second latch 354 is operated by the override pawl 500 (FIG. 3) and its associated mechanism, including the bail 510 (FIG. 4). The right-hand leg of the bail 510 is extended downwardly, forming a leg 615, as best shown in FIG. 8. The lower end of this leg carries a rightwardly extending pin 616 (see also FIG. 4) which is embraced within a slot 617 formed in the central section of a link 618. The link 618 is resiliently biased upwardly (clockwise in FIG. 8) by a suitable spring 619 and its forward end is pivotally secured to an arm 620 that is rockably mounted on a stud 621 on the right-hand side of frame plate 81 (FIG. 6). A second link 622 extends forwardly from the arm 620, the forward end of this link being pivotally connected to an arm 623 that is rigidly secured to the transverse shaft 532. Thus, the rocking of the override bail 510 is effective, through links 618 and 622, to rock arm 623 and shaft 532. The left end of this shaft is shown in FIG. 17 and carries an oddly shaped arm 626 on the extreme left end thereof. The extremity of the arm 626 underlies a pin 624 riveted on an offset tail portion 625 of the latch

354. Hence, the rocking of the override pawl 500 (FIG. 4), resulting from the attempted overshifting of the carriage, depresses slide 504, which rocks bail 510 (counter-clockwise in FIG. 8); and the rocking of the bail rocks the shaft 532 (counter-clockwise in FIG. 6 and clockwise in FIG. 17), thereby rocking the latch 354 to disengage the lever 356. Obviously the latch 354 will be rocked every time the override pawl is operated by an attempted left-hand shift of the carriage beyond its extreme end position. Ordinarily, this will have no effect on the machine operation as the lever 356 will be latched in its inoperative position by means of latch 355. It is only when the latch 355 has been disabled by the depression of one of the multiplier control keys that the rocking of latch 354 will enable a multiplication operation.

In connection with the description of the conventional multiplier mechanism which is given above, it should be noted that there is an idle cycle of operation immediately preceding the initiation of the actual multiplication operation. If the multiply key 66 is depressed, the depression of the key causes the engagement of the clearing clutch simultaneously with the rocking of shaft 438 to initiate a machine operation. In such a case, the first cycle of operation will clear the registers. During this cycle, the left shift mechanism is set to its effective position by the operation of the eccentric shown and described in connection with FIGS. 10 and 11. The actual shifting will then begin in the second cycle of operation and will continue until the carriage B reaches its extreme left-hand, or home, position. At this point, with the left shift control latched in its operative position, the machine continues to operate the left shift drive mechanism and, in the next succeeding cycle, operates the override mechanism already described. The operation of the override mechanism releases the first latch 354 (the second latch 355 having previously been released by depression of the multiply control key), and thus releases the multiplication initiating levers 344 and 356. In the event the carriage is in its home position when the key is depressed, the first cycle will cause a clearing operation if the key 66 was depressed and an idle cycle if the keys 67 or 68 were operated, and the second cycle will cause the initiation of operation of the override pawl. However, it should be noted that, in all instances, the override pawl is operated at about the midpoint of the cycle, and conventional interlocks prevent the setting of the digitation control gate until the end of that cycle. This idle cycle during which the override mechanism is operated, is important in our present invention as it enables us to set the machine for multiplication under the control of the storage dials 701 and to disable the conventional multiplier controls.

It is conventional in the machine of the Friden patents above-mentioned to terminate a multiplication operation by an attempted overshifting of the multiplier pin carriage to the right, which attempted shift rocks shaft 571 by means not pertinent here and hence not shown. The release of the multiplier control key 66, 67, or 68 by its respective latch enables the key to rise and all of the mechanisms positioned by its depression to return to their original positions. It will be recalled that the depression of either of these three keys has resulted in the rocking of shaft 438 (FIGS. 12 and 17), so that the release of the key enables this shaft to return to its normal position. The return rocking of this shaft through arm 1435 (FIG. 8) and lever 1437 releases the clutch control lever 281 and the switch control link 284, so that the motor is stopped and the clutch is disengaged at the end of that cycle of operation. Also, the return rocking of shaft 438 has disabled the mechanism shown in FIG. 10, by means of which the shift control shaft 511 was rocked to its operative position during the first cycle of operation. Thus, this shaft 511 is released from hook 1454 and the shaft is enabled to return to its normal, inoperative position at the end of the then current cycle. In the conventional machine the multiplication initiating levers 344

and 356 (FIG. 17) are simultaneously returned to their latched position by means shown in the Friden patents. This mechanism is replaced in our invention and will, therefore, be described in connection with our invention under Section IIE, Subsection 4(g).

13.

Storage Register

(FIGS. 1, 2, 8, 12, 20 and 21)

As shown in FIG. 1, the present invention is adapted to use the storage register dials 701 of the Malavazos patent, No. 3,045,907, previously mentioned, for the control of multiplication operations. The storage register comprises a series of ordinally arranged dials 701 visible through windows 700 and preferably aligned with the respective orders of the keyboard 50. As shown in FIG. 1, it is preferred also that these dials be arranged in the forward part of the machine in front of the conventional "0" keys 61.

The dials and their mountings can be of any suitable type, but we prefer to use ordinally spaced dials rotating in a substantially vertical plane and journaled on longitudinally extending shafts axially aligned with the orders of the keyboard. The several dials are mounted on individual shafts, not clearly shown in the drawings, which shafts (as best shown in FIG. 12) are suitably mounted on a flange member 705 bolted on, or otherwise rigidly secured to, a front transverse frame plate 706 extending across the front of the machine between the right-hand frame plate 81 and the auxiliary frame plate 83. Each dial is formed with an integral drive gear 707 by means of which the dials are severally rotated.

These storage dials, in the preferred embodiment of our invention, are driven from the coordinal square selection shafts 222 (FIG. 2). The mechanism for so driving the several storage dials 701 from their respective square shafts is best shown in FIGS. 2 and 12 and comprises a series of ordinally arranged drive shafts 710, preferably located immediately below the coordinal selection slides 210 and 211 and coaxial with the respective square shafts 222. These shafts are connectable to the square shaft through their several clutches, generally indicated at 711. The forward end of the shafts 710 is journaled in a bearing plate 712 rigidly mounted on the front end of the base plate 80. Various forms of mounting the rear ends of these shafts and of clutching them to the square shafts could be suggested, but we prefer the simple arrangement shown in the Malavazos patent. In this form, the several shafts 222 are extended through the cross plate 84 and the forward ends are made circular and of reduced diameter. A cylindrical driven clutch member 713, preferably provided with ten equiangular spaced notches, as shown, and with an axial bore extending throughout the length thereof, is pinned to, or otherwise rigidly mounted on, the rear end of the several shafts 710. The forward ends 720 of the several square shafts lie within the central bore of the coordinal clutch members 713, the forward ends 720 of shafts 222 forming bearings for the clutch members 713 and drive shafts 710 which are rotatable with respect to the square shafts. The several shafts 710 and their respective clutch members 713 are thus rotatably mounted with respect to the square selection shafts on which they are mounted, and each is driven by a driving clutch plate 714, preferably formed with two diametrically opposed jaw teeth adapted to fit snugly into the notches formed in the driven member 713. This driving plate is slidably but nonrotatably mounted on the respective selection shaft 222 and is shifted into, or out of, driving engagement with the driven members by means of clutch control levers 1074 (FIGS. 2 and 12). These levers, one at each side of the keyboard, are rigidly mounted on a transverse shaft 1075 journaled in bearing brackets 1076 affixed to the bearing plate 84. The two arms carry a bail 1077 which is formed as a comb with the teeth extending into an annular slot 1078 formed in

each of the driving clutch members 714 (the construction of the bail not being shown in these drawings but described in the Malavazos patent). Thus the rocking of the bail 1077, which is controlled by the rocking of the levers 1074 (counterclockwise in FIGS. 2 and 12) is effective to engage the clutches 711 and operatively connect the ordinal drive shafts 710 to the coordinal square, or selection, shafts 222.

The various shafts 710 are provided with a miter gear 715 (FIG. 24) rigidly secured thereto and located to the rear of, and adjacent to, the bearing plate 712. These gears 715 severally mesh with corresponding miter gears 716 (see also FIG. 12) mounted on the lower ends of a series of substantially vertical shafts 717. These shafts are journaled at their upper ends in the cross plate 706 and adjacent their lower ends in a second cross plate 718 rigidly mounted between the right-hand frame plate 81 and the auxiliary frame plate 83. Each vertical shaft carries a miter gear 719 at its upper end which is constantly in mesh with the gear 707 secured to the coordinal dial 701. Thus the operation of the clutches 711 connect the various dials 701 to their respective square shafts 222, whereby the incremental rotation of the latter will provide a corresponding rotation of the dial.

It will be understood that means is provided for clearing the respective dials 701, or returning them to a "0" registration, by any suitable means. The clearing mechanism is not pertinent to the present invention, and so will not be described. However, it should be understood that such a mechanism is included in the machine of our invention, as described in the Malavazos patent already mentioned.

II. STORAGE DIAL MULTIPLICATION MECHANISM

The present invention relates to a multiplier mechanism which utilizes the values standing in the storage dials 701 as the multiplier factor. This mechanism is so designed that it returns the dials 701 (preferably from the lowest to the highest orders thereof) serially to "0," while controlling the conventional multiplying mechanism to repeatedly enter the keyboard value additively or subtractively into the accumulator register dials 71. When the operative one of the storage dials 701 is returned to "0," the carriage shift control mechanism is actuated to interrupt digitation, to shift the carriage register B one order to the right, and to operate the control mechanism so that the next higher dial becomes effective to control the repeated operation in the next ordinal series.

In the present invention, it is preferred that the multiply key 800 (FIG. 1) and the squaring key 801 condition the machine for multiplication from the storage dials 701, but that the actual multiplication operation is initiated by depression of the conventional multiplier keys 66, 67 or 68. The depression of either of these keys initiates the conventional carriage shifting operation, either with or without clearing of the register dials 71, and the operation of the override pawl and its associated mechanism will, in the idle cycle of operation, disable the conventional multiplier controls and enable the controls of the present mechanism. Thereupon, the machine will be repeatedly cycled under the control of the values standing in the storage dials 701, while entering the keyboard value into the accumulator register either additively or subtractively.

A. General Arrangement

(FIGS. 1 and 20 to 23)

Preferably, this mechanism is designed to be readily added to the mechanism of the Malavazos machine described in the patent mentioned above. Thus that machine can be sold as a complete machine in itself, or, by adding the mechanism hereinafter to be described, can be converted into one which will use the back transferred value as a multiplier, selectively and at the will of the operator. For this purpose, the mechanism of the present invention

is mounted in a frame comprising a pair of brackets 810 and 811 (FIGS. 20 to 23) which are rigidly mounted on the auxiliary frame plate 83 and the right-hand frame plate 81 by any suitable means, such as machine screws 812 (FIG. 6). The various parts of the mechanism of the present invention are supported on a number of transverse shafts which extend between, and are journaled in, these auxiliary side frames 810 and 811. Preferably a plurality of intermediate supporting brackets 813 (see FIGS. 21, 24 and 25) are used to strengthen and align the respective shafts and related mechanisms. One preferred form of such brackets is the bail 814 shown in FIG. 21, which is rigidly mounted on the base plate 80 by any suitable means, such as screws 815, the legs of the bail being formed as the supporting and bearing brackets 813.

In the present invention, a miter gear 820 (FIGS. 12, 20, 24 and 25) is mounted on the extreme forward end of each of the shafts 710, preferably immediately forwardly of the bearing plate 712. Constantly meshing with each of these gears 820 is a larger miter gear 821. Preferably the gears heretofore mentioned and associated with the ordinal drive shaft 710 (such as the gears 715, 716, 719, 707 and 820) have been ten-tooth gears. However, the gears 821 are desirably twenty-tooth gears and hence considerably larger than the others mentioned. This larger size is convenient as, in our invention, it is essential to sense the return of this gear to a "0" position and the sensing mechanism can be made to conventional tolerances if the larger gear is used. The larger gears 821 thus have two angular positions representative of each of the digital values, including "0".

The large gears are provided with an integral hub 822, the right-hand face of which is provided with a series of twenty jaw teeth 823. The gears 821 and their respective hubs are rotatably mounted on bearings 825 (FIG. 25) carried on a transversely extending square feed shaft 824. The square shaft 824, as will be described more in detail hereafter, is inoperative in all operations of the machine except in multiplication under control of the storage dials 701, and during the operation of the present invention, is fed in increments of one step, or digital value, with each cycle of machine operation. However, the gears 821 normally remain stationary throughout the operation, being held in their adjusted positions by the conventional spring ball detent which engages the star wheel 721 (FIG. 12) on the various drive shafts 710.

The various gears 821 are adapted to be clutched to the square feed shaft 824 by ordinarily arranged clutches 830, which are slidably but nonrotatably mounted on the square shaft 824, as best shown in FIG. 25. These members 830 are preferably provided with a pair of diametrically opposed jaw teeth 831 adapted to engage any of the interdental spaces in the associated teeth 823 of the coordinal hub 822. The driver clutch members 830 are resiliently biased into engagement with the coordinal gears 821 by springs 832 which ride on circular sleeves 833 slidably and nonrotatably mounted on a second square shaft 834. These springs 832 encircle their respective sleeves and are seated against a flange, or collar, 839 nonsildably mounted on the square shaft 834, and their left ends are seated against a clutch control arm 835 which is rotatably mounted on the sleeve 833. These arms 835 extend downwardly and rearwardly, as best shown in FIG. 24, and at their lower ends are bifurcated to form a yoke which lies within an annular notch 836 formed in the driving member 830 of the clutch. A sensing arm 837 is rigidly mounted on the left end of each of the sleeves 833. Each of these sensing arms carries a roller 838 at its lower end, which is adapted to engage a pair of "0" notches 826 formed in the gears 821. Normally, all of the clutch control assemblies, including the sleeves 833, the rotatably mounted clutch-engaging arms 835, and the sensing arms 837, are held to the right by a comb 930, the operation of which will be hereafter described. In multiplication operations of the present invention, this comb is released for

5

movement to the left, whereby the assemblies are biased to the left by their respective springs 832. Thereafter, all except one are held in an inoperative right-hand position by means of ordinarily arranged cams 945, which will also be described hereafter.

In the preferred form of our invention, the storage register dials are not automatically cleared upon depression of either the multiply entry key 800 or the squaring entry key 801 (FIG. 1). In both instances, the keys initiate a single cycle of operation, in which a keyboard value is set into the storage dials, and the machine conditioned for multiplication under the control of these dials, the actual multiplication operation being initiated by depression of the multiplier initiating keys 66, 67 or 68. It obviously would be undesirable to automatically clear these dials if the value standing in the storage dials 701 was one that had been transferred into them by a back transfer operation from either the accumulator dials 71 or the counter dials 73, as described in the Malavazos patent. In that event, the multiply key 800 is depressed to condition the machine for operation under the control of the storage dials in the following multiplication operation, in which event the main keyboard 50 necessarily first must be cleared so that no value can be entered from the keyboard into the storage dials. In this situation, the cycle initiated by depression of the multiply key 800 is an idle one, except for conditioning the machine for operation under the control of these dials as multiplier storage members.

30

B. Key Mechanism

(FIGS. 8, 9, 12 and 13)

The multiplier entry key 800 and the squaring entry key 801 are identical and operate in almost identical programs to transfer the value standing in the main keyboard 50 into the storage dials 701, if a value is standing in the keyboard. The only difference between the programs initiated by these two keys, i.e., the multiply entry key 800 (FIGS. 8 and 9) and the squaring entry key 801 (FIGS. 13 and 20), is that the latter disables the "add" key mechanism, if that mechanism has been set to its operative condition. In many respects, both keys are similar to the back transfer control keys of the application heretofore mentioned. In each case, the key is mounted at the upper end of a substantially vertical key stem 725 which extends through aligned apertures in the cross plates 706 and 718, and the lower end of each key stem is formed as an ear, or bracket, 727 on which is riveted a pin 728.

In each instance, the pin 728 lies in a slot 733 formed in the forward ends of a pair of arms 734 and 735, respectively. Both arms are pivotally mounted on a transverse cross shaft 736 journaled in a pair of brackets 741 mounted on the rear side of the front cross plate 91. Each arm 734 and 735 is biased to an inoperative position (counter-clockwise in FIG. 8 or clockwise in FIG. 12) by a spring 742 tensioned between a seat formed in the arm and an opposed seat attached to the base plate 80, thereby holding the respective keys in their raised and inoperative positions.

Each arm 734 and 735 is provided with a rightwardly extending ear 743 and 744, respectively (best shown in FIG. 4), each of which engages the forward edge of a leg of a transversely extending bail 885 pivotally mounted on the shaft 736. Thus, the bail 885 will be rocked by the rocking of either arm 734 resulting from the depression of either the multiply entry key 800 or the squaring entry key 801, and, when so rocked, will be effective to operate various controls hereinafter described.

Each of the key stems 725 is also provided with a forwardly extending ear 745, as shown in FIGS. 9 and 13. Associated with these ears 745 is a latching slide 844 which extends across the front of the machine and is mounted for longitudinal movement transversely of the machine. Any suitable mounting could be used, but the simple form shown in these figures is preferred. This

75

comprises slots 845 in the slide 844 embracing pins 846 carried by brackets 847 formed on the lower cross plate 718. The slide 844 is biased to the right of the machine by a suitable spring 848 tensioned between the right-hand end of the slide and any suitable means, such as a spring seat in a third bracket 849 formed on the bottom plate 718. This slide is provided with a pair of latching projections 850, which projections are formed at their upper edges with a cam face 851 engaged by the associated ear 745 to cam the slide to the left against the tension of spring 848 upon depression of either key, and a shoulder 852 adapted to latch over the ear 745 and thereby hold the respective key in a depressed and operative position. Thus, the depression of either conditioning key 800 or 801, results in the key being latched in a depressed position by the engagement of the ear 745 on the key stem engaging under the shoulder 852 on the latching slide.

The latching slide can be moved leftwardly to release the depressed keys, either manually or automatically. Adjacent each of the conditioning keys 800 or 801, we prefer to provide a corresponding release key, such as 858 (FIG. 9), or 859 (FIG. 13). These keys are mounted on stems 860 extending through apertures in the top and bottom cross plates 706 and 718 and biased to a raised, or inoperative, position by any suitable means, such as the spring 861 surrounding the key stem of key 858 and seated between the key and the top cross plate as shown, or a spring 862 tensioned between the top cross plate 706 and an ear formed on the key stem of key 859. Each key is provided with a pin 863 adapted to engage the cam edge 864 of an upstanding finger 865 formed on the slide 844. Thus, the depression of either release key 858 or 859 is effective to cam the latching slide 844 to the left, and thereby release the depressed conditioning key 800 or 801. The slide 844 also can be translated to the left to release either depressed key 800 or 801 by automatically operated means at the end of a multiplication operation, as will hereinafter be described under the heading of "Condition the Terminating Mechanism for Operation" (Section E(4)(g) hereafter).

In the preferred construction of the multiplying and squaring keys 800 and 801 and their respective clearing keys 858 and 859, it is preferred that the depression of the clearing key will also depress the associated setting key. Thus, the depression of clearing key 858 will also depress the multiply setting key 800 (FIG. 9). This is readily accomplished by forming the key stems 860 of the key so as to overlie and abut a pin 867 carried on the lower end of the key stems 725 (FIGS. 9 and 13). Thus, the depression of the clearing key 858 or 859, through the engagement of the end of the key stem with the pin 867, also depresses the associated setting key. This construction is preferred in order to enable an entry of a keyboard value into the storage dials 701 by a single cycle of operation without leaving the machine conditioned for multiplication. Obviously, the keyboard value could be entered into the accumulator register in a conventional manner and then back-transferred from the register into the storage dials. This could be done, also, by depression of the multiply setting and squaring keys 800 and 801, and after the cycle is completed to clear the mechanism by subsequent depression of the clearing key 858 or 859. It is obviously more convenient to set these values directly into the storage dials. However, the preferred single cycle operation can be readily accomplished by having the conditioning keys 800 and 801 depressed by their associated clearing keys, whereby the machine is cycled from the conditioning keys, as will hereinafter be described, and the keys immediately restored to their inoperative position by the translation by the latching slide 844 to prevent latching of the conditioning keys.

C. Main Clutch and Motor Switch Control
(FIGS. 5, 8, 12)

The depression of either of the multiplying or squaring entry keys 800 or 801, respectively, is also effective to initiate machine operation by causing the engagement of the main drive clutch 270 (FIG. 6) and the closing of the motor switch. It perhaps should be mentioned that these two control keys which relate to the present invention, utilize the same means for initiating machine operation as the back transfer keys (keys 700, 1240 and 1400) of the said Malavazos Patent No. 3,045,907, and that the operation so initiated is limited to a single cycle of operation. This switch and clutch control mechanism comprises an arm 757 (FIGS. 8 and 12) which is pinned to, or otherwise rigidly mounted on, a transverse rockshaft 758. This rockshaft is journaled in bearing brackets (not shown in the present drawings but which are described in the Malavazos patent) mounted on the base plate 80. The arms 757 (FIGS. 8 and 12) are provided at their distal, or free, ends with a slot 760 adapted to cooperate with the pin 728 previously mentioned. This slot is provided with a projecting lower jaw 761 which underlies the pin 728 and a shortened upper jaw 762. When the shaft 758 is rocked by any one of the other keys which operate it, all of the arms 757 are rocked with it. The upper jaw 762 is so formed, that it (the upper jaw 762) passes beneath the pin 728 and thereby blocks depression of all of these keys so long as the one is operated.

An arm 767 (FIG. 5, which corresponds to FIG. 7 in the Malavazos patent above-mentioned) is rigidly mounted on the extreme right-hand end of shaft 758, to the right of the control plate 88. This arm carries a pawl 768 which is pivotally mounted thereon by any suitable means, such as pin 769. The pawl is biased to an operative position (clockwise in this figure) by any suitable means, such as a spring 770 tensioned between an ear on the pawl and a pin on the arm, as shown. The rearward end of the pawl is provided with a shoulder 771 normally abutting against a pin 772 carried by the rearwardly projecting portion 774 of a rocker arm 773. The rocker arm 773 is pivotally mounted on the right-hand control plate 88 by any suitable means, such as screw stud 784. The upper arm of the rocker 773 supports the forward end of a rearwardly extending link 775 which is pivotally connected thereto by any suitable means, such as pin 776. The rear end of this link is provided with a slot 778 which embraces a stud 779 to provide a pin-and-slot connection, permitting forward and rearward translation of the link 775. The link is provided with an upwardly extending shoulder 777 adapted, when the link is moved rearwardly, to engage an ear 291 (see FIG. 6) on the link 280 which connects the main clutch control pawl 274 to the control lever 281. Hence, the rearward translation of the link 775, occasioned by the rocking of shaft 758, causes the shoulder 777 to engage ear 291 and push the control link 280 to its operative position to cause engagement of the clutch and the closing of the motor switch, as previously described.

It is obvious that the rocking of the shaft 758 (counterclockwise in FIG. 5) pulls the pawl, or link, 768 forwardly (or to the left in this figure). Such movement of the pawl causes the shoulder 771, which engages pin 772, to rock the lever 773 (clockwise in FIG. 5) and translate the link 775 rearwardly. In the preferred form of our invention, the rocking of the rocker 773 is assisted by a light key touch mechanism which becomes effective as soon as the rocker has moved through a slight angle. This mechanism preferably comprises a V-shaped latch lever 790. This member is pivoted at the extremity of its lower arm to the right-hand control plate by any suitable means, such as stud 791, and is biased to an effective position (clockwise in this figure) by a relatively strong spring 792 tensioned between the divergent end of the

other arm and a stud on the frame plate. A roller 793 located at the elbow of the latch member 790 normally lies in a notch 794 formed in the lower end of the rocker 773. Rearwardly of the notch 774 the rocker is provided with a V-notch cam edge 795 extending upwardly and rearwardly at an oblique angle, as shown. Normally, this latch lever is latched in the position shown by the engagement of its roller 793 with the shoulder of notch 794. However, a slight movement of the rocker causes the roller to pass from under the shoulder of notch 794, whereupon the spring 792 becomes effective to rock the lever 790. Such rocking, through the engagement of the roller 793 with the cam edge 795, rocks the rocker to its extreme position to cause engagement of the clutch and the operation of the motor.

The mechanism just described is restored to its original inoperative position at the end of the first cycle of operation. Preferably the restoring means comprises a roller 780 mounted in the full-cycle position on a conventional gear 781. The gear 781 is rotatably mounted on the control, or auxiliary, plate 88 by any suitable means, such as screw stud 782, and constantly meshes with a driving gear 783 rigidly mounted on the main drive shaft 255. Thus, shortly before the end of the first cycle of operation, the roller 780 engages the end of link 775, forcing it forwardly, or to the left in FIG. 5, so as to restore the rocker and release the clutch and switch control mechanism. When this happens, the cam edge 795 forces the roller 793, and the latch on which it is mounted, downwardly to their normal, cocked position.

All of the operations initiated by rocking of the shaft 758, except that initiated by entry key 800, should automatically disable the add key mechanism in the event that such mechanism is set to its operative condition. It is obvious that a squaring operation, which involves a multiplication of a value by itself, requires retaining the keyboard value in the keyboard while entering it into the storage dial 701. Hence, in squaring, the add key mechanism should be disabled automatically, so that if it has previously been set to an operative condition, it cannot operate to clear the keyboard. On the other hand, a multiplication operation normally employs the multiplication of one value (in the keyboard) by another (in the storage register dials 701), and hence the keyboard should be automatically cleared at the termination of the entry operation. This is readily accomplished by the mechanism shown in FIG. 8.

The add key disabling shaft 171 (FIG. 6) is operated by the multiplier keys in the prior conventional machines. In the preferred embodiment of the present invention it is also operated by the rocking of the shaft 758. This is readily secured by mounting an arm 872 (FIG. 8) on the shaft 171 immediately to the left of the right-hand frame plate 81. An ear 873 on the lower end of this arm normally lies within a notch 874 formed in the upper edge of an arm 875. This arm is pivotally mounted on an arm 876 by any suitable means, such as pin 877. The arm 876, in turn, is rigidly mounted on the shaft 758, immediately to the left of the right-hand frame plate 81. Normally the arm 875 is biased to the upper position shown in which the ear 873 lies within the notch 874 by means of a torsion spring 878. The arm 875, at its forward end, is provided with an ear 879 which underlies the pin 728. Thus, the depression of the multiplier entry key 800 causes the pin 728 to engage the ear 879, and thereby rock the arm 875 (clockwise in FIG. 8) against the force of torsion spring 878, and thereby move the notch 874 to a position below ear 873. Normally, as ear 873 lies in notch 874, the rocking of shaft 758 rocks shaft 171 (counterclockwise in FIG. 8 and clockwise in FIG. 6) to disable keyboard clearing link 150. However, when the "Enter Multiplier" key 800 is depressed, the rocking of shaft 758 is unable to cause rocking of the shaft 171 as arm 872 is disengaged from notch 874, so that the rocking of arms 876 and 875 is ineffective. On the other hand, 75

if a squaring operation is desired and the key 801 is depressed, the rocking of shaft 758 to initiate a machine operation, automatically and simultaneously rocks shaft 171 to disable the add key mechanism and thereby block a clearing of the keyboard keys 50

D. Set Keyboard Value into Storage Dials

(FIG. 12)

It has been mentioned that the multiply entry key 800 and the squaring key 801 are effective to operate a bail 885 by means of their respective ears 743 and 744 which overlie the right-hand leg 886 and the left-hand leg 887 of the bail (FIGS. 4, 8 and 12). This bail is pivotally mounted on the shaft 736 and, as best shown in FIG. 4, the two legs thereof lie immediately to the right of their respective key-operated arms 734 and 735. It is preferred that ears 743 on the two operation initiating arms 734 and 735 rather closely engage the respective legs 886 and 887 of the bail, so that there will be little lost motion between the operation of either of the keys 800 or 801 and the rocking of the bail—as contrasted to a decided lost motion connection between these two keys and the operation of shaft 758 to the switch-closing and clutch-engaging position. The left-hand leg 887 (FIG. 12) of the bail pivotally supports a rearwardly extending link 888, the two members being pivotally secured together by any suitable means, such as pin 889. The rear end of this link is formed as a shoulder 890 adapted to engage a pin 891 carried by the lower end of the clutch setting lever 1074. Thus the rearward translation of link 888, which is caused by the depression of either key 800 or 801 and the consequent rocking of bail 885, is effective to rock the clutch control lever 1074 (counter-clockwise in FIG. 12) to its clutch-engaging position. This occurs prior to the engagement of the machine clutch and the closing of the motor switch, so that the machine operation initiated by depression of either key is subsequent to the engagement of clutch 711.

It is preferred that means be provided to limit the engagement of clutch 711 to a single cycle of operation. This is readily effected by resiliently biasing the link 888, as by means of spring 892, to a lower position in which the lower edge of the rear end of the link engages the pin 891. In the preferred form of our invention, we provide an upwardly and forwardly extending projection 897 extending from a rearward section of the link 888. A roller 898 is rotatably mounted on the extremity of this projection. A cam 899 pinned to, or otherwise rigidly secured on, the shaft 1427 lies in the plane of the roller 898. Thus, when the link 888 is translated rearwardly and the machine is cycled, the single lobe of cam 899 engages the roller 898 shortly before the end of the cycle and positively lifts the rear end of the link 888. When this occurs, the lever 1074 is snapped to its normal position (shown in FIG. 12) by conventional springs, not here shown. When the cam disengages the roller, the rear end of the link is permitted to drop, but when that occurs the pin 891 lies forwardly of shoulder 890, so that the continued depression of the key, with the continued rocking of bail 885, is ineffective to keep the clutch 711 in engagement. Thus, the operation of the clutch 711 is limited to a single cycle in the present invention. It will be recalled that the switch-closing and clutch-engaging mechanism is also limited to a single cycle, so that even if the key is maintained depressed, the machine will cycle once and no more; and will keep the clutch 711 engaged for a single cycle, and no more.

It is believed obvious that, with the clutch 711 engaged and the machine operated the single cycle above-mentioned, the keyboard value will be entered directly into the storage dials 701. It is obvious that the depression of the value keys 50 sets the selection gears 220 or 221 to a differential position determined by the key depressed. The subsequent cycling of the machine, and the consequent rotation of the drive shaft 255, causes the

actuators 250 or 251 (FIG. 2) to drive the selection gears 220 or 221 and their respective square drive shafts 222 through an incremental angle determined by the value key operated. If the clutch 711 is engaged during the differential rotation of square shaft 222, it is obvious that the storage dial 701 and the respective gear 821, will be rotated through the same differential angle. Thus, the value originally indexed into the keyboard will be set into the storage dials in the single cycle of operation occasioned by the depression of either key 800 or 801.

It should be further noted that in the present invention this entry of a value into the storage dials 701 is not accompanied by a shifting of the carriage or the clearing of any register. The only operation controlled by the depression of these two keys 800 and 801 is to cause the engagement of the clutch 711 for a single cycle of machine operation and to cause the machine to make this single cycle of operation. It will be recalled, however, that the keys are latched in their depressed position and are held latched until they are released by the operation of their respective clear, or release, keys 858 or 859, or automatically by termination of a multiplication operation. This latching of either key in its depressed position conditions the machine (as will hereafter be described) to control the subsequent multiplication operation from the storage dials and their connected mechanism rather than from the multiplier segments 315 upon the operation of the override pawl and its connected mechanism; but such latching of these keys does not initiate any further operation. That is, the depression of either key initiates a single cycle of machine operation during which the keyboard value is entered into the storage dials 701, and conditions the machine for multiplication under the control of the storage dials; but the initiation of the multiplication operation is caused by depression of the conventional multiply control keys 66, 67 or 68.

It should also be noted that the depression of either the multiply entry key 800, or the enter squaring key 801, is identical, except for the fact that the squaring key 801 disables the conventional add key mechanism, so that the keyboard value is retained in the keyboard at the end of this cycle of operation. On the other hand, the depression of the "Enter Mult" key 800 does not disable the operation of the conventional add key mechanism, so that the keyboard value is erased at the end of the cycle—if the add key mechanism is set to its operated position.

It should be understood that in the preferred form of our invention we do not automatically clear the storage dials 701 from the depression of either key 800 or 801. This could be readily done if thought desirable. However, to provide such automatic clearing would either require additional control keys, which are undesirable; or would prevent the use of a value back-transferred from either the accumulator dials 71 or the counter dials 73 into the storage dial 701. In its preferred form our present invention is designed to use the storage dials of the back transfer machine of the Malavazos patent above-mentioned, and to use a back-transferred value as a multiplier when desired. In such an event the keyboard is cleared, as by depression of the keyboard clear key 59. Then the operation of the key 800 cycles the machine, which, in this instance, is an idle cycle, as there is no keyboard value to be set into the storage dial 701. Those dials, therefore, still retain the back transferred value. This cycle of operation does, however, condition the machine for subsequent operation under the control of these dials rather than the multiplier segments 315.

E. Condition Machine for Multiplication Under Control of Storage Dials

(FIGS. 4, 8, and 14 to 24, inclusive)

The right-hand leg 886 of the bail 885 is formed as a rearwardly projecting tail 905 (best shown in FIG. 8). A horizontally extending ear 906 (see also FIG. 4) is formed on the rearward extremity of this tail, which car-

underlies and supports the forward end of a link 907. The rear end of the link 907 is pivotally secured to an arm 908 by any suitable means, such as stud 909. The arm 908 is pinned to, or otherwise rigidly secured on, the shaft 511. A torsion spring 910 encircling the pin 909 and engaging both the arm 908 and the link 907 tends to enlarge the angle between the two members, i.e., rock the link 907 clockwise in FIG. 8. An L-shaped slot 911 formed in the forward end of the link 907 has a horizontal rearwardly extending leg and a downwardly extending forward leg, as shown. A pin 915 that is rigidly affixed to the lower end of an arm 916 rockably mounted on the frame plate 81 by some suitable means, such as pin 917, normally lies in the angle of the two legs of the L-shaped slot 911. In normal operations of the shaft 511, the link 907 will be reciprocated forwardly (or to the right in FIG. 8). In this event, the pin 915 rides in the horizontal portion of the L-shaped slot, so that the rocking of arm 908 and translation of link 907 have no effect on arm 916. However, the rocking of bail 885, from the depression of either the multiply key 800 or squaring key 801, lifts the forward end of link 907, so that the pin 915 lies in the bottom of the vertical leg of the slot. In that event, the rocking of shaft 511 and the consequent rocking of arm 908 and translation of link 907 is effective to rock the arm 916.

It will be recalled that the rocking of shaft 438 from the depression of any of the multiplier control keys is effective to operate the mechanism shown in FIGS. 10 and 11. This mechanism includes the eccentric hook 1453 which, at the end of the first cycle of operation, engages the pin 1455 on arm 1456 and hence rocks shaft 511 (counter-clockwise in FIG. 10 and clockwise in FIG. 11) at the end of this first, or idle, cycle of operation. The shaft 511 is held in the rocked position throughout the multiplication operation and is not released until the key is released and the multiplication operation completed. In the present invention, such rocking of shaft 511 is effective to rock the arm 916. However, in normal operations, even normal multiplication operations in which shaft 511 is rocked, the arm 916 is not rocked because the pin 915 normally lies in the horizontal leg of the slot.

The pin 915 which is carried on the lower end of arm 916 and is embraced within the slot 911, preferably is used to support the rear end of a link 918 (best shown in FIG. 6). The forward end of the link 918 is pivotally connected to a lever 919 by any suitable pivotal connection, such as pin 920. The lever 919 is pivotally mounted on the right-hand side of the bracket 811 by any suitable means, such as a stud 921. The upper end of the lever 919 is slotted, as at 922, to embrace a pin 923 carried by arm 924. The arm 924 is pinned to, or otherwise rigidly mounted on, a transverse cross shaft 925. The shaft 925 extends entirely across the machine, being journaled in the brackets 811 and 819, as shown in FIGS. 20 and 21, and extending through, and being journaled in, an extreme left-hand bracket 816 (FIGS. 14 and 26) which is mounted on the left-hand control plate 89.

It will be obvious that the rocking of shaft 511 at the end of the first cycle of a multiplication operation as a result of the rocking of shaft 438 and the operation of the eccentric hook 1453 of the automatic clearing and leftward shifting mechanism shown in FIG. 10, will, through the linkage just described, be operable to rock shaft 925 at the end of the first cycle of operation. The rocking of shaft 925 is effective to: (1) enable operation of the ordinal dial clutches (drivers 830 already mentioned); (2) enable the drive means for returning the ordinal multiplier assemblies to a "0" position; (3) enable a holding pawl to hold the cam shaft 946 which controls the sequential ordinal operation of the clutch drivers 830 in each adjusted position; and (4) sets a dial multiplier control mechanism, which, in turn, is effective to (a)

disable the conventional shift control arm 317, i.e., disconnect it from control arm 325; (b) disable the conventional multiplier carriage shifting mechanism but not the shifting mechanism for the carriage B; (c) disable the conventional segment feed pawl 316; (d) condition register carriage right shift clutch for operation (the shifting operation being initiated by rocking of the shaft 375 to control the shifting operations of the register carriage in multiplication from the return of the operative one of the storage dials 701 to "0"); (e) enable operation of the auxiliary carriage shift mechanism upon return of the operative dial to "0"; (f) enable incremental rotation of cam shaft 946 during interordinal shifting operation; and (g) condition a multiplication terminating mechanism for operation as soon as all of the dials have been returned to a "0" condition. These various operations will now be described in this sequence and under the respective headings given above.

(1) *Enable operation of ordinal dial clutches (FIGS. 20 to 25, inclusive).*—Normally, all of the clutch drivers 830 are held disabled, against the force of their respective springs 832, by a disabling comb 930. This comb is slidably mounted in apertures in the intermediate bracket 810 and the right-hand bracket 811. It carries a single tooth 931 in each ordinal position, the various teeth engaging their respective sensing arms 837, as is best shown in FIG. 20. The left end of the comb 930 carries a roller 932 (best shown in FIG. 23) preferably lying immediately to the left of the intermediate bracket 810. This roller is engaged by the land, or straight portion, of a cam arm 933 (see also FIG. 25). This arm is pivotally mounted on the transverse cam shaft 946, but is held against axial movement therealong by a suitable collar 934. The upper end of the cam arm 933 is provided with a slot 935 (best shown in FIG. 23), which slot embraces a pin 936 carried by an arm 937, that is pinned on, or otherwise rigidly secured to, the transverse conditioning shaft 925. The lower end of the cam arm 933 has a trailing and rearwardly directed cam nose 938 offset to the left (as best shown in FIGS. 21 and 25). Thus, the rocking of the shaft 925 (counter-clockwise in FIG. 6 and clockwise in FIG. 23) rocks the arm 933 so that the pin is no longer held by the land, or straight portion, of arm 933 but is engaged by the laterally offset cam nose 938. Thereupon, the comb 930 is enabled to move to the left from the force of any one of the springs 832. It should be noted here that only one of the clutches is allowed to become engaged at any one time, the clutches being operated sequentially, as will be explained in the next paragraph. Therefore, such movement of the disabling comb 930 releases the respective clutch drivers 830 to the control by their co-ordinal control cams, and only one of them (preferably the lowest order) will be operative.

The sequential operation of the respective ordinal clutch drivers 830 is controlled by a series of ordinarily arranged cams 945 which are pinned to, or otherwise rigidly secured on, a transverse cam shaft 946 (see particularly FIGS. 21, 22, 24 and 25). The cams are identical in shape and comprise a disk portion perpendicular to the axis of the shaft with an offset tail, or cam nose, 947, stamped therefrom. This type of construction leaves a gap between the end of the nose 947 (as best shown in FIG. 24) and the trailing edge 948 of the flat disk portion. The offset cam noses 947 have a lateral dimension sufficient to enable movement of the clutch drivers 830 into firm engagement with the clutch teeth 823 formed in the hub of the large miter gears 821. The cams are helically arranged around the cam shaft 946 (best shown in FIG. 21), being angularly separated one from another by angles of 36° in the ten-order machine illustrated. The faces of the cams engage an upstanding nose 840 of the respective arms 837, and thus, normally hold the clutch arms 835 in an inoperative position (to the right) except when the nose 840 engages the offset tail 947 of the cam. The noses 840 of the arms 837 are engaged by

the flat face of the disk, or dwell, of their respective cams 945 throughout a major portion of a cycle and are hence held (to the right in FIG. 21) against movement by their respective springs 832, and thereby hold the respective clutch drivers 830 disabled. However, when the nose 840 passes the trailing edge 948, the spring 832 snaps the arms 835, 837 to the left until stopped by the tail 947 of the cam. In that position the driver 830 engages gear 823 and the incremental feed of shaft 824 restores the gear toward its "0" position. When the cam shaft 946 is rotated another increment, the cam 945 moves to the next ordinal position, whereupon the nose 840 is engaged by the slope of the cam nose 947 and is returned to its disabled position.

Thus, the release of the disabling comb 930 and its consequent movement to the left from the force of one of the springs 832, releases one, and only one, clutch driver 830 for engagement with its respective driven member. The particular one of the drivers to be so engaged is, of course, controlled by the angular position of the cam shaft 946. In our preferred form of construction the shaft 946 is normally resiliently held by a relatively strong spring in the angular position in which the lowest order clutch driver 830 is enabled to engage its driven member at the start of a multiplication operation, the cam shaft 946 being angularly fed, or rotated an angular increment of 36° during each ordinal shifting operation of the carriage B, as will be explained in the next section, and is held in the adjusted position by a holding pawl which will be released at the termination of the multiplication operation to return the shaft 946 to its home position.

(2) *Enable the drive means for returning ordinal multiplier assemblies to a "0" position (FIGS. 14, 18, 20, 21, 24 and 25).*—It has already been mentioned that the large miter gears 821 (FIGS. 20, 21, 25) are rotatably journaled on the square, or feed, shaft 824, and are directly geared to the coordinal storage dials 701 through gears 820 and 715 on the main shaft 710. In the present invention, in each ordinal series of operations, the square shaft 824 is rotated through a single value increment, or 18° in each machine cycle. In all of the orders except one, the dials and the connected large miter gears 821 are held in their set value position by the conventional, 40 detents on the drive shaft 710 (which in FIG. 12 comprises the star wheel 721 and the associated spring-pressed ball, not shown or identified). In the operative order, however, the miter gear 821 is clutched to the shaft through the leftward translation of the clutch driver 830 into the 45 position in which the diametrical teeth 831 of the driver engage in the interdental spaces of the cooperating jaw teeth 823 formed on the hub of the miter gear 821. Thus, the rotation of the square shaft 824 a single value increment, i.e., 18°, will be effective to rotate the coordinal storage 50 dial 701 through a similar single value increment (i.e. 36°, for it will be remembered that gears 821 have twenty teeth while gears 820, with which they mesh, have ten). In the preferred form of our invention, the square shaft 824 is rotated (counter-clockwise in FIGS. 24 and 18) 55 to return the coordinal storage dial 701 toward "0" a single value increment in each cycle of operation. It can be noted again that as the dial returns to the "0" position, a sensing means is operated which causes termination of operation of the driving mechanism for rotating shaft 824, 60 the shifting of the carriage B, and the rotation of cam shaft 946 a single increment to place the mechanism under the control of the adjacent higher order dial by disengaging one clutch driver 830 and engaging the adjacent driver.

The means for enabling the drive for the square shaft 824 from the rotation of shaft 925, and the means for so driving the square shaft, are best shown in FIG. 18. Approximately halfway between the intermediate bracket 810 and the left-hand bracket 816 (as is shown in FIG. 14), the conditioning shaft 925 carries an arm 953 which is pinned to, or otherwise rigidly secured on, the shaft.

The extremity of the arm 953 carries a pin 954 (see also FIG. 18) which is embraced within a slot 955 formed in the upper end of a bellcrank member 956 which is rotatably mounted on a bearing (not shown) on the square shaft 824. Obviously the rocking of shaft 925 (counter-clockwise in FIG. 18) will be effective to rock the bellcrank 956 (clockwise in this figure). The rearwardly extending arm of the bellcrank 956 carries a roller 957 which supports the forward end of a feed pawl 962. The forward end of this feed pawl 962 lies within a slot formed in a guide bracket 963 mounted on the base plate 80. The forward end of this feed pawl 962 is provided with a laterally turned ear 964 adapted to engage the teeth of a feed ratchet 965 which is pinned to, or otherwise rigidly mounted on, the square shaft 824.

The rear end of the feed pawl 962 is pivotally connected to a rocker 970 by any suitable means, such as pin 971. The feed rocker 970 is pivotally mounted on the auxiliary left-hand frame plate 90 by any suitable means, such as a screw stud 972. The forward end of the rocker 970 is pivotally connected to an eccentric cam follower 1480 by some suitable means, such as pin 973. The eccentric follower 1480 encompasses an eccentric 1481 rigidly mounted on the main drive shaft 255. In the conventional machine, the feed pawl 316 is mounted on an interponent extending between the pin 973 on the eccentric follower 1480 and the feed pawl member. However, in the present invention, the feed pawl 316 is pivotally secured to the forward arm of rocker 970 by some suitable means, such as pin 1482, so that both the rocker 970 and the feed pawl 316 are reciprocated by the same means with each cycle of machine operation. Normally, the feed pawl 316 is held disabled by a disabling arm 321 and the feed pawl 962 is held disabled by the roller 957 on bellcrank 956. In all conventional multiplication operations, the disabling arm 321 is rocked (counter-clockwise in FIG. 18) to enable the feed pawl 316, and thereafter acts as a holding pawl for the ordinal segment 315. The rocking of arm 321 still takes place in the present multiplication operation as it is affixed to shaft 387 which is enabled by operation of control levers 344 and 356 (FIG. 17), but the feed pawl 316 is disabled by the means described in Section 4(c) entitled "Disable Conventional Multiplier Segment Feed Pawl." The feed pawl 962 is controlled by the operation of two members: The rocking of the bellcrank 956 from the rocking of the bellcrank 956 from the rocking of the conditioning shaft 925 in the first, or clearing, cycle of the multiplication program; and the roller 979 on the lower end of the arm 978 (FIG. 15) which is affixed to shaft 387. The shaft 387 is normally in the position shown in FIGS. 14, 15 and 17, whereby the feed pawl 962 is disabled. However, the operation of the latches 355 and 354 (FIG. 17) and the consequent rocking of the control levers 356 and 344, acting through link 360 and arm 365, rock the shaft 387 (clockwise in FIGS. 15 and 17) to move the roller 979 to an unblocking position. When both the arm 978 and bellcrank 956 are thus rocked, the feed pawl 962 becomes effective. At the end of an ordinal cycle of operation, the shaft 387 is returned to the full line position shown (counter-clockwise in FIG. 15) through the operation of the shift control arm 325 already mentioned. Thus, the feed pawl 962 is disabled at the end of each ordinal cycle of operation.

It is obvious from the above description that both the feed pawl 962 and the conventional feed pawl 316 are reciprocated with each cycle of machine operation. In all conventional operations, including conventional multiplication, the reciprocation of feed pawl 962 is idle in that the ear 964 is at all times lifted above engagement with ratchet 965 by the bellcrank 956 (which is shown in its normal position in FIG. 18). However, the rocking of shaft 925 (counter-clockwise in this figure) and the resultant rocking of bellcrank 956 (clockwise in this figure) enables ear 964 to engage the teeth of ratchet

965 and thereafter the reciprocation of pawl 962 is effective to rotate the shaft 824 in increments of 18° in each cycle.

It can be noted here that the feed pawl 962 will be disabled during the carriage shifting cycle by means of the arm 978 (FIG. 15) which is pinned to the multiplier control shaft 387. This arm carries the roller 979 (shown in both FIGS. 15 and 18) which engages the lower edge of the link 962, when the shaft 387 is in its normal position shown, and holds the feed pawl 962 disabled. However, when the shaft 387 is rocked at the start of the actual multiplication operation to normally enable the feed pawl 316 for an ordinal series of operations, the arm 978 is also rocked (clockwise in FIG. 15) to simultaneously release feed pawl 962. Whether the conventional feed pawl 316 or the new feed pawl 962 is permitted to operate is subject to the controls here being described. It should be noted here that when the control arm 325 (FIGS. 15 and 26) is rocked, by means hereinafter described, at the end of each ordinal series of operations, the shaft 387 will be rocked in the conventional manner to disable feed pawl 962 during the cycle in which the carriage B is shifted and control of the sequential operations is changed from one dial 701 to the next. That is, when a dial 701 returns to "0" and the shaft 387 is rocked (counter-clockwise in FIG. 15), the roller 979 lifts the forward end of feed pawl 962 so that the feed is terminated until after the shifting cycle is completed.

It is obvious that the operation of the feed pawl 962, when the shaft 925 is rocked to enable the ear 964 to engage the ratchet 965, is effective to rock the shaft 824 an increment with each cycle of operation. The rocking of this shaft (counter-clockwise in FIGS. 18 and 24) is effective to rotate whichever miter gear 821 is clutched thereto a single value increment, and thereby return the ordinal dial 701 one step toward its "0" position. When the "0" position is reached in any order, the mechanism to be described hereinafter under heading "4(e)" entitled "Enable Operation of Auxiliary Carriage Shift Control Mechanism Upon Return of the Operative Dial to 0," will become effective to control the shifting of the carriage and the rotation of the cam shaft 946 one increment.

It can be noted here that the shaft 824 is centralized in each angular position thereof by any suitable centralizing, or detenting, means. We prefer the simple centralizer and detent shown in FIG. 23 which comprises the star wheel 1170, the notches of which are engaged by a roller 1171 mounted on the lower end of an arm 1172. The arm 1172 is pivotally mounted on the intermediate bracket 810 by any suitable means, such as stud 1173, and is biased into engagement with the star wheel by a suitable spring 1174. Thus, the star wheel 1170, and consequently shaft 824, are held in the proper angular positions necessary for operation of the machine.

(3) *Enabling holding pawl for cam shaft 946 (FIGS. 14 and 27).*—A third effect of the rocking of shaft 925 during the first cycle of a multiplication operation, i.e., during the "idle" cycle, in which the shifting mechanism is conditioned for a carriage left shift operation, is to enable a holding pawl for the cam shaft 946. It was mentioned previously that the cam shaft is under considerable spring tension to return it to its home position in which the first order cam enables the first order clutch to engage its driven member. The mechanism for holding the cam shaft 946 in an adjusted position is best shown in FIGS. 14 and 27. Adjacent the left-hand bracket 816, the conditioning shaft 925 carries an arm 985 which is pinned to, or otherwise rigidly secured thereon. The arm 985 carries a pin 986 on its outer end, which pin engages the back of the upper leg of a bellcrank 987, which is mounted on a pivot stud 988 secured to the bracket 816. A spring 989 tensioned between the lower leg of the bellcrank 987 and the arm 985 resiliently biases the bellcrank against the pin 986. In its normal position, the arm 985 holds the bellcrank 987 away from

a ratchet 990 that is pinned to, or otherwise rigidly secured on, the cam shaft 946. The lower leg of the bellcrank 987 is formed as a pawl to engage the teeth of ratchet 990, so that when the shaft 925 is rocked (counter-clockwise in this figure) and the bellcrank 987 is enabled to rock (clockwise in this figure) from the force of spring 989, the end of the lower leg of the bellcrank will act as a pawl to hold the ratchet 990 in any adjusted position.

A drum 991 is secured to the ratchet 990 so that the two turn together with shaft 946. A belt 992 has one end rigidly fastened to the drum whereby the belt winds upon the drum as this drum is rotated incrementally. A spring 997 (FIG. 26) tensioned between the rear end of the belt 992 and a stud on the base plate 80 exerts considerable force against the turning of shaft 946 and returns the shaft 946 to its home position immediately upon the disabling of the holding pawl 987.

Preferably a return stop is associated with the ratchet 990 and drum 991 to prevent overthrow in the return movement of the drum and shaft 946. A simple stop (shown in FIG. 27) comprises a three-armed lever 993, which is pivotally mounted on the bracket 816 by any suitable means, such as stud 994. A spring 995 tensioned between one arm of the stop lever and a stud on the bracket, holds the stop in the clockwise position shown, in which the lower arm abuts against the pin 988. In this position, the forward arm overlies a pin 996 mounted on the left-hand face of the drum 991. The drum and ratchet 991, 990 are fed in a clockwise direction in FIG. 27 by the mechanism to be described in Section 4(f), and is returned in a counterclockwise direction at the termination of the operation by the force of the spring 997 pulling on belt 992. When the pin 996 engages the forward arm of the three-armed lever 993, it is obvious that the drum must stop rotating as the other arm has engaged the pivot pin 988. On the other hand, during the rotation in a clockwise direction, when the pin 996 engages the nose of the forward extending arm 993, the three-armed lever can rock against the tension of spring 995 and permit an additional step of movement. This is sufficient, as for ten ordinal spaces and at the extreme movement the cam shaft 946 and pin 996 which occurs when the tenth, or highest, order dial 701 is effective to control operation, the pin will lie in the same position as shown, the drum having made a complete revolution. At this point the arm 993 is rocked out of the way and cannot operate as a stop to prevent rotation of the shaft to this angular position; but it will act as a stop upon the reverse rotation at the completion of the operation.

(4) *Set dial multiplier control mechanism (FIGS. 14, 26 and 28).*—The fourth operation caused by the rocking of the conditioning shaft 925 is to set the mechanism which conditions the machine for multiplication under the control of the values in the storage dials 701. It will be understood that the mechanism described in this subsection is operated at substantially the same time as the mechanisms in the three preceding subsections—the rocking of the shaft 511 (FIGS. 8 and 10) from the eccentrically mounted hook, and consequently the rocking of shaft 925, occurring at roughly about the midpoint of the first machine cycle, as is conventional. This is an idle cycle of operation and is used to condition parts for the succeeding multiplication operation. It is desired that this conditioning be done relatively early in the cycle, so that all the control parts effected thereby can be set in operative condition before the cycle ends. It is conventional in these machines, as is well understood by those familiar with the art, that conventional interlocking devices are incorporated in the machine (although not shown and described herein) which prevent these various control mechanisms from becoming effective until the end of the current idle cycle—these mechanisms becoming effective as the drive shaft 255 returns to its full-cycle position (actually about the 350° position) and before

digitation can begin in the next succeeding cycle (which starts at about the 15° position), as the machine cycles continuously.

The mechanisms for setting the dial multiplier controls are best shown in FIGS. 14, 26 and 28. These mechanisms are also set to an operative position by the rocking of the conditioning shaft 925. At its extreme left end, this shaft carries a pair of operating arms 1001 and 1002, which can be constructed as an offset bellcrank or as two separate arms individually pinned to the shaft 925 (as shown in FIG. 14). In either event, the two arms are rigidly mounted on the shaft 925 and hence are rocked (clockwise in FIGS. 26 and 28) by the rocking of shaft 925. The upwardly extending arm 1001 is pivotally connected to a long link 1003 by any suitable means, such as pin 1004. Preferably, the link 1003 is offset to the left, as shown in these figures, in order to enable the mechanism shown in FIGS. 26 and 28 to lie on the left, or outside, of the conventional multiplier mechanism shown in FIG. 17 (all of the conventional mechanisms already being mounted relatively close to the left-hand control plate 89). The rear end of the link 1003 is provided with an elongated slot 1005 which embraces a pin 1010 riveted on, or otherwise rigidly secured to, the upper end of an arm 1011 that is rigidly mounted on a control shaft 1012. The control shaft 1012 (as shown in FIG. 14) is journaled in bearings in the left side control plate 89 and left side frame plate 82 and passes through an aperture in the intermediate frame plate 90 (see FIG. 14). Thus, the rocking of the shaft 925 (clockwise in FIGS. 26 and 28) is effective to rock the shaft 1012 in the same direction. The rocking of this shaft is effective to: (a) disable the conventional multiplier shift control lever 317 by disconnecting it from its associated control lever 325; (b) disable the multiplier pin carriage shift; (c) disable the conventional multiplier segment feed pawl; (d) condition register carriage right shift clutch for operation from rocking of shaft 387; (e) enable operation of auxiliary carriage shift mechanism upon return of the operative dial to "0"; (f) enable incremental rotation of cam shaft 946 during interordinal shifting cycle; and (g) condition the terminating mechanism for operation as soon as an all "0" condition is sensed in the storage dial 701. These various aspects will now be discussed in that sequence.

(a) *Disable conventional multiplier shift control lever 317 (FIGS. 14 and 17).*—The shaft 1012 carries a disabling arm 1013 rigidly secured thereto, preferably to the right of, or inside of, the left side control plate 89. The rocking of the arm 1013, as a result of the rocking of the shaft 1012, is effective to rock a second disabling arm 1014, which is pivotally mounted on the right side of the control plate 89 by any suitable means, such as stud 1015. The two arms are operatively connected one to another by any suitable means, preferably by a pin-and-slot connection comprising a pin 1016 carried by the upper end of the arm 1013 engaging a slot 1017 formed in the lower end of the lever 1014. The upper end of the lever 1014 has a pin 1018 riveted on, or otherwise rigidly secured to, the upper end thereof, which pin engages the forward edge of the tail 331 of the interponent 327. Thus, the rocking of shaft 1012 and arm 1013 (clockwise in FIG. 17) rocks the disabling lever 1014 (counter-clockwise in this figure), thereby rocking the interponent 327 (clockwise) to disable the connection between the two sections 317 and 325 of the conventional multiplier shift control lever. The forward section 317 of this lever is thereby enabled to assume either position without effecting control of the multiplication operation. It will be recalled that the rearward section 325 of this lever is connected to the multiplier control mechanisms through link 370 (FIG. 15) and this portion will be operated as hereinafter described in Sub-section e.

(b) *Disable conventional multiplier pin carriage shift (FIGS. 14 and 19).*—A bellcrank 1024 is pinned to, or

otherwise rigidly mounted on, the right end of the shaft 1012. In the normal position of the parts (shown in FIG. 19), the forwardly extending arm of the bellcrank lies in a position above the conventional multiplier carriage shift mechanism shown in this figure and comprising the arms 388, 389 and 390 already described. However, when the shaft and bellcrank are rocked (counter-clockwise to the dotted line position shown in this figure) the forward edge 1025 of the horizontal arm 1045 of the bellcrank is rocked downwardly to lie immediately behind the pin 393, and hence block rotation of the interponent 390. In that event, the rocking of the shift control shaft 375 can take place as usual, arm 389 rocking with the shaft. However, the spring connection 391 between the arm 389 and interponent 390 enables the 15 rocking of the interponent to be positively blocked. In this manner, during the multiplying operation under control of the storage dials 701, the conventional shift arm 388 remains disabled, although the shift control shaft 375 will operate in the conventional manner.

(c) *Disable conventional multiplier segment feed pawl (FIGS. 14 and 18).*—A forked arm 1033 is pinned to, or otherwise rigidly mounted on, the control shaft 1012 in a plan adjacent to the conventional feed pawl 316. Normally, the shaft 1012 and the blocking arm 1033 are held in their disabled angular positions by a spring 1034 which is tensioned between the offset rearwardly extending arm 1035 and a pin 1036 riveted to the right side of the intermediate left side frame 90. The forward arm 1037 of this forked lever 1033 is provided with a laterally offset ear 1038 which is adapted, when the shaft 1012 is rocked (counter-clockwise in FIG. 18), to engage the offset tail portion 322 of the feed pawl 316. That is, upon rocking of the shaft 1012 from its normal inoperative (full line) to its operative (dashed line) position, the forked arm 1033 blocks operation of the conventional feed pawl 316. It will be recalled that the bellcrank 979 is rocked in each cycle of machine operation, and normally this rocking will enable the operation of the feed pawl 316 whenever the disabling arm 321 is rotated to the multiply position. However, when the multiplication operation is under the control of the storage dials, the feed pawl 316 is disabled by the ear 1038, even though the arm 321 and its control shaft 387 are rocked in the conventional manner. At this time, of course, the feed pawl 952 is enabled to feed the ratchet 965 one increment of 18°, as that pawl was enabled by the rocking of shaft 925 and, in the override cycle, by the rocking of shaft 387, as heretofore explained. Thus, the rocking shaft 1012 has disabled the conventional feed pawl, and the auxiliary feed pawl 952 has been enabled so that the multiplication operation will proceed under the control of the storage dials.

(d) *Condition register carriage right shift clutch for operation (FIGS. 4, 14, 16 and 19).*—The lower end of the vertical arm 1027 of the blocking bellcrank 1024 is formed as an offset bracket 1039 (FIGS. 14 and 19). This bracket carries a downwardly projecting roller 1040 (FIG. 19) which normally lies in the lowermost section 1044 of a cam depression 1049 of a control arm 1045 (FIG. 16). The cam arm is pivotally mounted on a bracket 1046 which extends to the right from the left side frame plate 82 by any suitable means, such as the bolt 1047. The forward end of the lever 1045 is provided with an upstanding ear 1048 (FIG. 16) which is interposed between the left-hand end of the shift control bail 401 and the right-hand side frame of the multiplier carriage. When the carriage is in its normal, or home, position, the lower part of the cam depression 1044 will be one ordinal space removed from the pin 1028, as shown in FIG. 16. When the multiplier carriage is shifted to the left, the arm 1045 can rock one increment to enable the shift control bail 401 to shift to the left and enable a right shift of the carriage B from rocking of shaft 375. However, in the present invention, it must

be assumed that the shifting of the multiplier pin carriage is, of course, disabled, for in many instances the multiplier pin carriage will remain in its home position. However, in our invention the shaft 375 will be rocked at the 5 end of each ordinal series of operations, and so can be used to initiate the carriage shifting operation. We utilize the rocking of bellcrank 1027 for this purpose. When the bellcrank 1024 is rocked rearwardly (counter-clockwise in FIG. 19), the roller 1040 is moved along the 10 cam face 1049 on the arm 1045, thereby rocking the arm (counter-clockwise in FIG. 16). Such rocking of the arm obviously shifts the shift control bail 401 to the right.

It has previously been mentioned that the carriage shifting control arm 399 (see FIG. 4), which is carried on shaft 375, lies opposite an offset portion 404 of pin 402, which pin lies against the front end of the right shift control rod 474 (see FIG. 11). Thus, the shifting of the bail to the left from the escapement of the conventional multiplier pin carriage enables the arm 399 15 to lie immediately adjacent the pin 402, while the rightward shifting of the bail from the rocking of arm 1045, just described, is effective to shift the arm 399 to the right, so that it lies immediately adjacent the coaxial section 405 of the pin 402. Thus, in either shifted position the arm 399 will, upon rocking of shaft 375, engage the pin 402 or aligned section 405, and hence enable a right shift of the register carriage B. On the other hand, when the arm 399 lies in the normal position shown in 20 FIG. 4, it is opposed to the offset section 404, so that rocking of the arm will be ineffective to move the pin 402, 405 and consequently will not enable a right shift of the carriage.

(e) *Enable operation of auxiliary carriage shift mechanism upon return of the operative dial to "0" (FIGS. 20, 21, 22, 24, 25, 26 and 28).*—Normally, the auxiliary shift control mechanism is disabled by a blocking arm 1055, which is rotatably mounted on the shaft 1012 (FIG. 26). Adjacent the blocking arm 1055 is a second arm 1056 which is pinned to, or otherwise rigidly secured on, the shaft 1012. A spring 1057, tensioned between ears on the arms 1055 and 1056, resiliently biases the blocking arm 1055 to follow rocking of the second arm 1056 to its blocking position (counter-clockwise from 25 the position shown in FIG. 28 to that of FIG. 26), when the shaft 1012 is returned to its normal position at the end of a multiplication operation. On the other hand, when the shaft 1012 is rocked by the power rocking of shaft 925, then the ear 1058 on the fixed arm 1056 positively lifts the blocking arm 1055 to its unblocking position (lifting it from the position shown in FIG. 26 clockwise to the position shown in FIG. 28). Thereafter, this mechanism is under the control of the "0" sensing mechanism which can be effective only in connection with 30 the storage dial which is operatively controlling the multiplication operation.

It will be recalled in connection with the discussion of the storage register that it was mentioned that each of the large miter gears 821 was provided with diametrically notches 826 which lie in the "0" position of the gears. Cooperating with these notches is the "0" sensing arm 837 and its roller 838 (see FIGS. 24 and 25). Normally, the "0" sensing arm 837 is held in an inoperative position with respect to its notch 826 (see the right-hand 35 order of FIG. 25) by the ordinal control cams 945. However, when the ordinal control cams 945 enable operation in a particular order of the register by clutching the clutch driver 830 to the hub of the miter gear from the lateral movement of clutch control arm 835 and "0" 40 sensing arm 837, then the roller 838 will engage the periphery of the miter gear 821. Thereafter, when the miter gear returns to its "0" position, the roller will be enabled to drop into the notch 826. This sequence is 45 shown in FIG. 24 in which the sensing arm 837 is shown in full lines in its normal inoperative position, and is 50

shown in two dotted-line positions, in the first of which (intermediate position) the roller 838 engages the periphery of the gear, and then the extreme counter-clockwise position in which it is engaging the notch 826. It will be recalled that only one clutch can be engaged at any one time, because of the helical arrangement of the cams 945, and that all of the "0" sensing arms 837 are held to the right in a disabled position except the one which is controlling the multiplication operation. It will also be recalled that the arm 837 is nonrotatably but slidably mounted on the square shaft 834 so that the rocking of an arm 837 will result in rocking of the shaft 834.

The shaft 834 is strongly biased to an operative, or "0" sensing, position (counter-clockwise in FIG. 24 and clockwise in FIGS. 26 and 28) by means of a relatively strong spring 1063 tensioned between the lower end of a lever 1064 mounted on the extreme left-hand end of the shaft 834 (see FIG. 26) and a stud on the base plate 89. The rocking of the shaft 834 from the force of spring 1063 is, of course, blocked by the engagement of a roller 838 engaging the periphery of the large miter gear 821 at all times, except when the roller can drop into one of the notches 826. However, when the roller of the operative order engages the associated notch 826, the shaft and sensing arm is enabled to rock (counter-clockwise in FIG. 24 and clockwise in FIGS. 26 and 28), whereupon the lever 1064 rocks in the same direction. The upper end of the lever is connected to a rearwardly extending link 1065 (FIGS. 26 and 28) by any suitable means, such as pin 1066. The rear end of the link 1065 is pivotally connected to the lower leg 1069 of a bellcrank control member 1067 by means of a long pin 1068. This pin cooperates with the rear end of the blocking lever 1055 (as shown in FIG. 26) to block the control mechanism in an inoperative position in all machine operations except multiplication under the control of the front storage dials. This bellcrank 1067 is mounted on the left-hand control plate 89 by any suitable means, such as stud 1070.

The other, or forwardly extending leg of the bellcrank is bifurcated, or Y-shaped, as shown in these figures. The upper portion 1084 of this leg is offset to the left (FIG. 14) and is provided with a pin 1085 which is embraced within a slot 1086 in the lower leg of a bellcrank 1087. The bellcrank 1087 is mounted on a long pin 1088 (see FIG. 14) mounted on the left side control plate 89. The upper leg of the bellcrank 1087 (when the machine is conditioned for operation under our invention, as shown in FIG. 28) barely engages a pin 1093 rigidly secured to an arm 1094 that is pinned to, or otherwise rigidly secured on, the control shaft 318. Normally, the bellcranks 1067 and 1087 are latched in the position shown in FIG. 26, which corresponds to the full line position of arm 837 in FIG. 24. When the dial multiplication mechanism is controlling the operation of the machine, these two bellcranks assume the position shown in FIG. 28, which corresponds to the intermediate position of the arm 837 (shown in FIG. 24 as the intermediate, or clockwise dotted line, position). In this condition, the upper arm of the bellcrank 1087 just engages the pin 1093. When the arm 837 is enabled to drop into the "0" notch 826 (assume the counter-clockwise dotted line position shown in FIG. 24), the two bellcranks 1067 and 1087 rock further (bellcrank 1067 rocking counter-clockwise and bellcrank 1087 rocking clockwise from the position shown in FIG. 28). Such operation of the bellcrank 1087, of course, rocks the arm 1094 (counter-clockwise in FIGS. 26 and 28). It will be recalled that the section 325 of the shift control lever is also pinned to, or otherwise rigidly mounted on, the shaft 318, so that the rocking of the arm 1094 rocks the arm 325 in the same direction and thereby initiates the interordinal program of terminating digitation in the then present ordinal position, shifting the carriage

one order to the right, and, in the present instance, enabling means for rocking the cam shaft 946 one increment to place the machine under the control of the next higher order storage dial 701.

This programming is secured from the rocking of the arm 325 (counter-clockwise in FIGS. 26, 28 and also in FIG. 15) which drops the hook link 372 down to engage the latch 378 (FIG. 15) and release arm 381. The release of arm 381 rocks shaft 375 on which it is secured and also the arm 382 which is rigidly mounted on shaft 375. The spring 383 pulls the arm 382 rearwardly (counter-clockwise in FIG. 15) to rock shaft 387 which normally disables the segment feed pawl. In the present operation, the rocking of shaft 387 is effective, through the rocking of arm 978 rigidly secured thereto, to lift the auxiliary feed pawl 962 (see also FIG. 18) to its disabled position. Thus, the rocking of the shaft 387 is effective to disable the auxiliary feed pawl 962 and hence interrupt the incremental rotation of the square shaft 824 which rotates the operative one of the large miter gears 821. The rocking of shaft 375 is also effective, through the carriage shifting mechanism heretofore described, to occasion a single order left shift of the carriage B. The rocking of the shaft 375 will also be effective to control the incremental rotation of the cam shaft 946, as will be described in the next subsection.

In the early part of the cycle following operation of bellcranks 1067 and 1087, that is, in the early part of the shifting cycle controlled by the operation of shift control lever 325, the two bellcranks are returned to their normal, or full-cycle, position shown in FIG. 26. It is seen that a restore cam 1099 is mounted on the extreme left end of the main drive shaft 255. This cam has an enlarged lobe 1098 with a rather steep rise beginning at the "0" position and terminating with an abrupt drop at about the 180° position. The periphery of this cam is adapted to engage a roller 1071 mounted on the straight portion 1089 of the arm 1084. The operative one of the ordinal gears 821 is returned to its "0" position at about the midpoint of a cycle, as the feed of shaft 824 takes place in the first part of each cycle. Thus, at about the midpoint of a cycle, an arm 837 senses the "0" condition of the coordinal gear 821 by the dropping of roller 838 into the "0" notch 826. This rocks the square shaft 834, so that at this point in the cycle the bellcranks 1067 and 1087 are rocked. This timing is not critical as the lobe 1098 of the cam will engage the roller 1071 and hold it in an inoperative position until the midpoint of the cycle is reached. Thereupon, the two bellcranks rock from the position shown in FIG. 26 to the operative position in FIG. 28 to immediately initiate operation of the parts controlled by the movement of shift control lever 325. Thus, the latter part of that cycle is used to condition the machine for the termination of digitation in that order, the shifting of the carriage, the rocking of the cam shaft 946, and any other control mechanism necessary before the end of a cycle. Thus, the next cycle immediately starts the shifting operation. As soon as this shifting cycle is begun, the roller 1071 will engage the rise of the lobe 1098, thereby restoring bellcranks 1067 and 1087 to their normal position. This positive rocking of these bellcranks obviously rocks the square shaft 834 to the overthrow position shown in solid lines in FIG. 24, to positively disengage the roller 838 from "0" notch 826 and thereby prevent any friction or binding of these two cooperating parts, as the rocking of the cam shaft 946 causes the operative cam to force the clutch control arms 835 and sensing arms 837 of the previously operative order, to the right (FIG. 25) to a disabled position and simultaneously enable the adjacent higher order cam to control the engagement of the next higher order clutch driver 830. The arm 837 is held in its extreme rocked, or overthrow,

position for a substantial portion of the cycle, so that the adjacent higher order clutch can become engaged and the adjacent higher order "0" sensing arm 837 will be spaced outwardly from the periphery of the higher order gear 821. Then as the cycle approaches its midpoint, the lobe 1096 releases the roller 1071, so that the parts are permitted to drop into their normal position in which the roller 838 engages the periphery of cam 821. As this occurs at the midpoint of the cycle, the sensing arm 837 is permitted to rock, immediately initiating a new shifting cycle, if it should happen that the new order should stand at "0." If not, then the parts are conditioned to enable the initiation of digitation immediately upon the start of the next cycle of operation.

(f) *Enable incremental rotation of cam shaft 946 (FIGS. 14, 26 and 28).*—It will be understood from what has preceded that the cam shaft 946 is rotated through an angle of 36° at the end of each ordinal series of operations, actually being rotated during the interordinal shifting cycle initiated by operation of bellcranks 1067 and 1068 resulting from the rocking of shaft 834. It is necessary, obviously, to rotate the cam shaft 946 an amount sufficient to rotate the previously operative control cam to an inoperative position and to rotate the adjacent higher order control cam to an operative position, which, in a ten-order machine, requires the angular displacement of 36°. The mechanism for so rotating the shaft 946 is best shown in FIGS. 14, 26 and 28. This mechanism comprises, in its preferred form, a ratchet gear 1101, preferably located at the extreme left end of the shaft 946 (as best shown in FIG. 14). This ratchet gear is rigidly mounted on the shaft 946 and its teeth are in angular alignment with the teeth of the holding ratchet 990, previously described. This ratchet is adapted to be moved through a single increment, preferably 36°, by a feed pawl 1102 which has a leftwardly extending ear 1103 adapted to engage the ratchet teeth of the ratchet gear 1101. The forward end of the feed pawl 1102 is held against lateral displacement by a slot in a guide bracket 1104. The rear end of the feed pawl 1102 is pivotally mounted on a supporting arm 1105 to which it is pivotally mounted by a pin 1106. The arm 1105, in turn, is rockably mounted on a stub shaft 1107 secured to the left-hand control plate 89. An eccentric cam follower 1103 is also mounted on the pin 1106, this follower embracing an eccentric cam 1109 that is rigidly mounted on the main drive shaft 255. Thus, the feed pawl is reciprocated with each cycle of machine operation.

Normally, the feed pawl 1102 is held in the disabled position shown in FIG. 26 by a roller 1115 mounted on the lower end of the arm 1002 which, as previously described, is rigidly secured on the initiating, or control, shaft 925. This roller 1115 holds the forward end of the feed pawl 1102 in its inoperative position during all machine operations except that of multiplication under control of the storage dials. When the conditioning shaft 925 is rocked (clockwise from the position shown in FIG. 26 to that shown in FIG. 28), this block is removed and thereafter the operation of the feed pawl is under the control of the shifting shaft 375, previously described. The shaft 375 has an arm 1116 pinned to, or otherwise rigidly secured thereon, preferably at the extreme left end thereof (see FIG. 14). A link 1117 has its rear end pivotally connected to the arm 1116 by any suitable means, such as pin 1118, and its forward end pivotally connected to a bellcrank 1119 by a suitable pivotal connection, such as pin 1120. The bellcrank 1119 is pivotally mounted on a stub shaft 1121, and at the extremity of its upwardly and forwardly extending leg, carries a roller 1122. In the normal position of the shaft 375, this roller 1122 holds the forward end of the feed pawl 1102 downwardly against the force of a torsion spring 1123 mounted on pin 1106 and seated against arm 1105 and feed pawl 1102 in a manner to lift the forward end

of the feed pawl 1102. Therefore, when the shaft 375 is rocked at the end of one ordinal series of operations (counter-clockwise in FIGS. 15, 26 and 28), the bellcrank 1119 is rocked in the same direction, whereupon the feed pawl 1102 is enabled to rise into engagement with the feed ratchet 1101. This enabling of the feed pawl occurs at the end of the cycle in which the operative gear 821 returns to its "0" position, with the consequent rocking of shafts 834 and 1064, the translation of link 1063, and the rocking of bellcranks 1067 and 1068 to enable the shift control member 325. Thereupon, in the next cycle of operation, the reciprocation of the feed pawl 1102 is effective to rotate the ratchet 1101 through an angular increment sufficient to disable the formerly operative cam 945 and enable the adjacent higher order cam. This rocking of the feed ratchet 1101 and shaft 946 is thus effective to shift the control of the multiplying mechanism from one order to the adjacent one.

(g) *Condition the terminating mechanism for operation (FIGS. 14, 24, 26 and 28).*—In the preferred form of our invention, a multiplication operation under control of the storage dials is terminated as soon as all of the dials stand at a "0" registration. It is, of course, obvious that the multiplication operation could be terminated by operation of the multiplier mechanism through all ten orders of the storage dials, being terminated only when the highest order had been sensed and returned to "0." It is preferred, however, to terminate operation as soon as all of the dials stand at "0," and such a mechanism is shown in FIGS. 14, 24, 26 and 28.

The termination of a multiplication operation is under the control of the terminating shaft 1130. This shaft carries a number of "0" sensing arms 1131 (FIG. 24) pinned to, or otherwise rigidly secured on, the shaft and aligned with the "0" notches 826 on the coordinal gear members 821. Each arm is provided with a nose 1132 adapted to engage the coordinal "0" notch 826 whenever all of the dials, and consequently all of the "0" notches, stand at a "0" position. It will be recalled that the gear members 821 are not shifted longitudinally on their shafts 824, so that all of the arms 1131 are always in the planes of the "0" notches 826. All of these arms 1131 are pinned to the shaft 1130 and all are in angular alignment, so that all of the arms and the shaft are held in the disabled position shown in full lines in FIG. 24, so long as any one of these arms engages the periphery of its gear. That is, it is only when all of the gears stand at a "0" position that the shaft 1130 can be rocked; and conversely, if any arm 1131 engages the periphery of its gear, such engagement will hold the whole assembly in a disabled position.

A bellcrank 1133 is mounted on the extreme left end of the shaft 1130 (FIGS. 14, 26 and 28). This bellcrank, and consequently the shaft 1130, are biased to a "0" sensing position (counter-clockwise in FIGS. 26 and 28) by a relatively strong spring 1134. A roller 1135 mounted at the rear end of the rearwardly extending arm of the bellcrank 1133 supports the forward end of a terminating link 1140. Preferably, the bellcrank 1133 is adapted to engage a pin 1006 on the arm 1002 when the shaft 925 is in its normal inoperative position. In that event, the bellcrank 1133 is held in the inoperative position shown in FIG. 26 by a pin 1005, regardless of the setting of the storage dials 701. It is only when the machine is conditioned for operation of the multiplication mechanism of the present invention that the bellcrank 1133 and shaft 1130 are released to become operative to sense the "0" position of all of the dials 701, as shown in FIG. 28.

70 The terminating link 1140 extends rearwardly, as shown in FIGS. 26 and 28, its rear end being supported on a suitable arm 1141 which is rotatably mounted on the stub shaft 1107 adjacent the arm 1105 previously described. The link 1140 and arm 1141 are pivotally connected to an eccentric cam follower 1142 by a common

pin 1143. This follower embraces an eccentric cam 1144 (FIG. 28) mounted on the main drive shaft 255 immediately adjacent the cam 1109. The forward end of the terminating link 1140 is provided with a shoulder, or nose, 1145, adapted to engage a roller 1146 mounted on the lower end of a terminating arm 1147 that is pinned to, or otherwise rigidly mounted on, the left-hand end of the multiplication terminating shaft 571. Preferably, the terminating link 1140 is biased to a lower position in which the nose 1145 can engage the roller 1146 by any suitable spring means, such as the torsion spring 1148. Thus, when all the arms 1131 are enabled to drop into their respective "0" notches 826, the shaft 1130 rocks (clockwise in FIG. 24 and counter-clockwise in FIGS. 26 and 28) thereby rocking the bellcrank 1133. When this happens, the terminating link 1140 is enabled to drop so that its nose 1145 will engage the roller 1146, and, at the end of that cycle of operation, will pull the arm 1147 rearwardly to rock shaft 571 and thereby terminate machine operation. As previously described, this termination occurs because the rocking of shaft 571 releases the latches for the multiplication keys (see FIG. 17), thereby enabling the keys to rise and, therefore, disabling all of the mechanism which controls a multiplication operation.

The rocking of the shaft 571 is also effective to release the depressed multiply key 800 or squaring key 801. It is seen in FIG. 14 that an arm 1155 is pinned to, or otherwise rigidly mounted on, the shaft 571. The forward end of this arm overlies the left end of a bellcrank 1156 (FIG. 13). Thus, the rocking of shaft 571 (clockwise in FIGS. 26 and 28) causes the rocking of the bellcrank 1156 (counter-clockwise in FIG. 13). This bellcrank is mounted on any suitable pivotal mounting, such as stud 1157, that is riveted on, or otherwise rigidly mounted upon, a bracket 1158 formed on the bottom plate 718. The upper end of the vertical arm of this bellcrank engages a pin 866 mounted on the latching nose 850 of latching slide 844. Thus, the rocking of the bellcrank (counter-clockwise in FIG. 13), through its engagement with stud 866, shifts the latching slide 844 to the left and thereby releases the depressed key. This key is thereupon raised to its inoperative position and the machine comes to rest.

F. Multiplication Operation

In order to condition the machine for a multiplication operation under control of a value set into the storage dials 701, the multiplier entry key 800 (FIGS. 1, 8 and 9) is depressed. If the multiplier factor is already in the storage dials, the conventional keyboard keys 50 should first be cleared by the operator. If the multiplier factor is a value which is transferred from the accumulator register dials 71 or the counter register dials 73, the back transfer operation will preferably have cleared the keyboard during such an operation. In the event that this was not the fact and the keyboard had been used for intervening factors, then it will be necessary for the operator to clear the keyboard as by depression of the keyboard clear key 59. If, on the other hand, the operator desired to enter a new factor into the front storage dial 701, such a factor would be set in the keyboard prior to the depression of the multiplier entry key 800.

In any event the depression of the multiplier entry key 800 will result in latching the key in its depressed position by means of the latching slide 844. The depression of the key 800 rocks the bent arm 734 (FIG. 8) which, in turn, rocks the bail 885. The rocking of the bail 885, through the rearward translation of link 888 (FIG. 12), rocks the clutch control lever 1074 to clutch-engaging position. This clutch, in its engaged position, connects the square selection shaft 222 to the storage dial drive shafts 710, so that the value standing in the keyboard

50 will be entered directly into the storage dial 701 in a single cycle of operation.

The depression of the multiplier entry key 800 is also effective to rock arm 757 and hence shaft 758 which, through the mechanism shown in FIG. 5, is effective to initiate a single cycle of machine operation. This mechanism, as was explained under the heading "Main Clutch and Motor Switch Control," Section C above, is positively released toward the end of that cycle of operation, so that one cycle of operation only can be secured, even though the key is latched in a depressed position. Likewise, the link 888, which controls the positioning of the clutch control shaft 1074, is disabled at the end of each cycle of operation by the operation of cam 899 (FIG. 12).

The depression of the multiply entry key 800 also rocks the arm 875 (FIG. 8) through the engagement of pin 728 with ear 879. When so rocked, the arm 875 cannot engage the arm 872 mounted on the "add" key disabling shaft 171, the rocking of which is effective to disable the conventional "add" key mechanism. Thus, the depression of the enter multiply key 800 is effective to prevent operation of the disabling shaft 171, so that the add key mechanism will operate at the end of the digitizing phase of that machine cycle and thereby automatically clear the keyboard for the entry of the multiplicand factor.

In the event the squaring key 801 is depressed, the operation is substantially the same, except that the arm 875 is not disabled. In that event, the disabling shaft 171 is rocked and the add mechanism is thereby disabled, so that the keyboard factor will remain in the keyboard and hence can be used as the multiplicand, and the factor can be squared. The depression of the squaring key 801 (FIGS. 1, 12 and 13) is effective to rock arm 73 and hence the bail 885, and is also effective to rock arm 757 which is rigidly mounted on initiating shaft 758. Thus, the depression of this key likewise initiates a single cycle of machine operation in which the operation is automatically disabled at the end of the cycle and causes engagement of the clutch 711 under control of the arm 1074, so that the keyboard factor is set into the storage dial 701 while being retained on the keyboard.

The rocking of the bail 885, resulting from the depression of either the multiply entry key 800 or the squaring entry key 801, also sets an interponent into operative position to condition the machine for a multiplication operation under control of the storage dials rather than the conventional multiplier mechanism when the multiplication operation is initiated by depression of the conventional multiply keys 66, 67 or 68. This interponent is shown in FIG. 8 and comprises the link 907 which is pivotally mounted on the arm 908 that, in turn, is rigidly secured on the setting shaft 511. The link 907 has an L-shaped slot 911 which embraces a pin 915 on the conditioning arm 916. The pin 915 normally rides in the horizontal section of the slot 911, whereby the rocking of the shaft 511 will not rock the arm 916. However, when the bail 885 is rocked from depression from either of the multiplier or squaring keys 800 or 801, the arm 905 of the bail lifts the forward end of link 907, and the pin 915 is locked in the vertical section of the L-shaped slot. Thereafter, the rocking of shaft 511 rocks arm 916, and hence the conditioning mechanism shown in FIG. 6, which comprises the link 918, lever 919, arm 924 and shaft 925. Incidentally, it can be noted that the shaft 511 is rocked by the shift and clearing control mechanism, shown particularly in FIG. 10, and is held in the rocked position until the multiplier key that initiated the multiplication operation is released—which occurs in the last cycle of the multiplication operation. Hence the shaft 925, and all of the conditioning elements controlled thereby, are held in an operative position throughout the multiplication operation.

In the event that it is desired to use a value transferred from the product register, or the counter register as a

multiplier, the conventional back transfer keys are operated and the factor back-transferred in a conventional manner. Then the depression of either of the multiply key 800 or the squaring key 801 is effective to initiate a cycle of operation that is idle in all respects, except that the link 907 will have been lifted to its operative position in which the rocking of shaft 511 will be operative to rock the control shaft 925.

After the multiplier factor has been set into the storage dials through the depression of the multiply entry key 800, the multiplicand factor will be set in the keyboard by the operator. In the event the squaring entry key 801 was depressed, this entry of the multiplicand is unnecessary, as the depression of that key results in the maintaining of the keyboard factor in the keyboard, so that this factor appears both in the keyboard and in the storage dials. In either event, the depression of one of the conventional multiply keys 66, 67 and 68 will initiate a multiplication operation. For the most part, the operation initiated by these keys will be substantially those of the Friden patents, Nos. 2,371,752 and 2,399,917 already mentioned. The depression of the conventional multiply control keys 66, 67 and 68 will result in setting the machine for positive, or negative, operation and for clearing, or nonclearing the registers in carriage B in the conventional manner. It will be recalled that the depression of one of these keys has been effective to release the first latch 355 that prevents operation of the multiplier mechanism, so that this operation is also the same as in the conventional machine. Further, the second latch 354 is rocked to a disengaging position by the operation of the override pawl 500 (FIG. 3), and this is likewise true in the present invention. The present invention actually initiates the multiplication operation by the rocking of control levers 356 and 344 (FIG. 17) and their connected control mechanisms. The termination of repetitive digitation in one order, the shifting of the carriage, and the initiation of repetitive digitation in the adjacent higher order, is controlled in the same manner as previously—the only difference being that in the present invention the operation is controlled from the return of the various ordinal gears 821 (FIGS. 24 and 25) to a "0" position instead of the return of an ordinal multiplier segment 315.

The rocking of the conditioning shaft 925 shifts the disabling slide 930 to the left so as to enable the various clutch control arms 835 from the force of their respective springs 832 (FIGS. 20, 24 and 25). The rocking of the control shaft 925 (FIG. 18) also enables the operation of the feed pawl 962 (which reciprocates in every cycle of machine operation, but ordinarily does so idly) to drive ratchet 965, and hence the feed shaft 824 which returns the operative one of the gears 821 toward a "0" position. The rocking of the shaft has also, through the mechanism shown in FIGS. 26 and 28, disabled the conventional multiplier shift control arm 317, so that its position no longer affects the interordinal program of multiplication. The rocking of the conditioning shaft 925 simultaneously sets a control shaft 1012 (FIGS. 26 and 28) which, among other things, disables the connection between shift control arms 317 and 325 and conditions arm 325 for operation by the return of a storage dial 701 to its "0" position, and thus control the interordinal programming from such dials. The rocking of the shaft 1012 is also effective to disable the conventional feed pawl which returns the conventional multiplier segments 315 toward a "0" position; has disabled the multiplier pin carriage shifting mechanism; has adjusted the carriage right shift control so that the rocking of the conventional shift control shaft 375 (FIG. 15) will be effective to initiate a right shift of the carriage, even though the multiplier pin carriage remains in its home position. In this condition, the machine operates in repetitive cycles in which digitation occurs additively or subtractively, as controlled by the selection of the keys

66 or 67 on the one hand or 68 on the other. When so conditioned, each cycle of operation of the feed pawl 962 (FIG. 18) is effective to rotate shaft 824 one value increment (in the preferred form 18°, as we prefer to use a control gear 821 with two series of ten digital value positions). When the operative gear 821 returns to a "0" position, the roller 838 on the coordinate arm 837 (FIG. 24) is enabled to drop into the notch 826 in the gear, thereby rocking shaft 834. The rocking of shaft 834 (counter-clockwise in FIG. 24 and clockwise in FIGS. 26 and 28), through link 1065, is effective to rock the bellcranks 1067 and 1037, thereby rocking the shift control member 325 to terminate operation in the then operative order and thereby control the shifting of the carriage B and the initiation of operation under the control of the next adjacent higher dial 701. The rocking of the control member 325 enables the hook link 372 (FIG. 15) to release latch 378 and thereby rocking of arm 381 and shaft 375. The rocking of shaft 375, in turn, rocks shaft 387, whereupon the arm 978, through its roller 979, lifts the feed pawl 962 to a disengaged position, thereby terminating the feed of a shaft 824. The rocking of shaft 375 is also effective, through the linkage shown in FIGS. 26 and 28, including the link 1117 and bellcrank 1119, to enable the feed pawl 1102 to engage its ratchet 1101, thereby rocking the ratchet and its shaft 946 one increment (preferably of 36°). The rocking of shaft 946 obviously rocks the ordinarily arranged control cams 945 that are mounted thereon (see FIGS. 21, 22, 24 and 25). These cams are staggered around the shaft 946 at equiangular increments, whereby only one of the cams can enable the operation of its coordinate clutch control arm 835. Thus, all of the clutches are disabled except one in the operative order.

When all of the gears 821 are returned to their "0" positions, this condition is sensed by the arms 1131 which are rigidly secured on shaft 1130. When the shaft 1130 is enabled to rock (clockwise in FIG. 24 or counter-clockwise in FIG. 22), which can only occur when all of the ordinal arms 1131 are enabled to fall into a "0" sensing notch 826, the bellcrank 1133 (FIG. 26) enables the terminating link 1140 to engage the roller 1146 on arm 1147. The rocking of arm 1147, and the shaft 571 on which it is mounted, releases the latches which hold the multiply initiating keys depressed, so that the return of these keys to their normal position can terminate machine operation in the conventional manner. The rocking of the shaft 571 rocks the clearing arm 1155 (see FIG. 14). The forward end of this arm (as shown in FIG. 13) overlies the horizontal arm of a bellcrank 1156 that is pivotally mounted on a suitable pin 1157 carried by a bracket 1158. The upper leg of the bellcrank engages pin 866, so that the rocking of the bellcrank is effective to move latching slide 844 to the left and release key 800 or 801 which is held depressed thereby.

The release of the multiplier initiating key, by enabling the return rocking of shaft 438 (FIG. 10), disables the mechanism which holds the shaft 511 in its rocked position. Thus, the shaft 511 is returned to its normal inoperative position at the end of that digitating cycle of operation, whereupon the shaft 925 is returned to its normal position. Such return of the shaft disables all the mechanisms controlled thereby, particularly disabling the holding pawl 937 (FIG. 27) which holds the cam shaft 946 in an adjusted position, whereupon the shaft is returned to its normal inoperative position by means of spring 997 (FIG. 26) which is tensioned between a stud on the base plate and the belt 992 secured to the drum 991 rigidly secured to the ratchet 990. Thus, the cam shaft 946 is returned to its original position in which the lowest order dial would be effective to control a multiplication operation when one is initiated.

While we have herein described, and in the drawings

shown, our preferred embodiment of the present invention, it is to be understood that the invention is not limited thereto, but may comprehend other constructions and arrangements without departing from the spirit of the invention. For example, we have shown this multiplication mechanism as embodied in a machine of the type shown in the Malavazos patent, No. 3,045,907, issued July 24, 1962, as already mentioned. However, it will be understood that the present invention could be associated with any type of a back transfer machine in which values transferred out of a product register or counter register, or both, can be set into a storage mechanism. In fact, the present invention can readily be included in a machine with a storage register, even though the so-called "back transfer" operation is not a part thereof, as it would be suitable for a multiplier storage register which could be set only from entries in the main keyboard of the machine. Thus, it is believed that the best results will be obtained with the construction and arrangements herein shown and described, but this is to be taken only as a preferred embodiment of the invention. It should, therefore, be understood that minor changes coming within the scope of the subjoined claims should be included within the scope and spirit of the present invention.

We claim:

1. In a calculating machine having an ordinally arranged value indexing mechanism, an ordinally arranged product register, digitation means for entering a value determined by said indexing means into said product register, means for shifting the relative ordinal positions of said product register and said value indexing means, and a cyclically operative drive means, the combination which comprises a rotatable shaft, a plurality of ordinally arranged storage cams rotatably mounted on said shaft, means for entering multiplier values into said storage cams, multiplier control means including a feed member for rotating said shaft, ordinal clutches for connecting said cams to said shaft, means operated by said drive means for incrementally operating said feed member to return said cams toward a "0" position, means for sequentially operating said ordinal clutches whereby only one of said clutches will be engaged at one time, means for sensing the return of an operating one of said cams to a "0" position, and means operated by said sensing means for disabling operation of said feed member and the operative one of said ordinal clutches, for operating said shifting means, for operating said sequentially operating means to enable the adjacent order clutch, and for initiating the reoperation of said feed means.

2. In a calculating machine having a value indexing mechanism, a product register, digitation means for entering a value set in said indexing means into said product register, a cyclically operative drive means for operating said digitation means, and means for shifting said product register relatively to said value indexing means, the combination comprising a plurality of ordinally arranged storage members; means for entering multiplier values into said storage members; ordinally arranged cam members respectively connected to the coordinal storage members; restoring means including a common feed member, means operated by said drive means for incrementally operating said feed member, and ordinal clutches for connecting said feed member to said storage members and cams to return said storage members and cams toward a "0" position; means for sequentially operating said ordinal clutches whereby only one of said clutches can be engaged at any time; means for sensing the return of an operating one of said storage members and cams to a "0" position; means operated by said sensing means for disabling said feed member and the operative one of said ordinal clutches, for shifting said product register, for enabling an adjacent order clutch, and for enabling the reoperation of said feed member; means for sensing the "0" position of all of

said cams; and means operated by said last mentioned sensing means for terminating operation of said drive means and for returning said sequential operating means to its original condition.

5. In a cyclically operable calculating machine having a value indexing mechanism, a product register, digitation means for entering a value set in said indexing means into said product register, means for shifting the relative ordinal positions of said product register and said value indexing means, a plurality of ordinally arranged storage dials, means for entering multiplier values into said storage dials, and a cyclically operative drive means for operating said digitation means and said shifting means, a multiplying mechanism comprising a rotatable shaft, ordinally arranged cam members rotatably mounted on said shaft and respectively geared to the coordinal storage dials, means operated by said drive means for incrementally rotating said shaft in a direction to return said cams to "0" position, ordinal clutches for connecting said shaft to said cams, means for sequentially operating said ordinal clutches whereby one only of said clutches will be engaged at one time, a first sensing means for sensing the return of an operative one of said cams to a "0" position, a second sensing means for sensing the "0" position of all of said cams, means operated by said second sensing means for terminating operation of said drive means, and means operated by said first sensing means for disabling incrementally rotating means and the operative one of said ordinal clutches, for operating said shifting means, for enabling the sequentially operating means and thereby enable an adjacent order clutching means, and for enabling the reoperation of said feed means.

4. In a calculating machine having a value indexing mechanism for storing a multiplicand value, a product register, means for shifting said product register relative to said value indexing means, a digitation mechanism effective to enter values determined by said value indexing mechanism into said product register, and power means for operating said digitating means and said shifting means selectively, a multiplication mechanism comprising a set of ordinally arranged storage members, means for inserting multiplier values into said storage members, a zero-cam member operatively connected to each of said storage dials, a common feed shaft extending along said set of storage members, ordinally arranged clutches adapted to clutch said common shaft to the coordinal one of said cam members, normally disabled means for incrementally rotating said common shaft in a direction to return said cams toward a "0" position, a cam shaft, ordinally arranged cams spirally mounted on said shaft for controlling the operation of said clutches whereby said cams are operative sequentially to enable one only of said clutches and sensing members at one time, means for resiliently biasing said shaft to a position in which the lowest order cam is effective to enable the lowest order clutch, normally disabled means for incrementally rotating said cam shaft, a latch for holding said cam shaft in an adjusted position, a first zero-sensing member associated with each of said cam members and operative to sense a "0" value position of the coordinal cam member, a second zero-sensing means for sensing a "0" value position of all of said cam members, a multiply key, means operated by said key for enabling the incremental rotation of said feed shaft, means operated by an operative one of said sensing members when sensing a "0" condition of the coordinal cam member to disable the incremental rotation of said feed shaft and to enable the incremental rotation of said cam shaft, and means operated by said second sensing member for terminating operation of said power means and for releasing said latch.

5. In a calculating machine having a value indexing mechanism for storing a multiplicand value, a product register, means for shifting said product register relative

55

to said value indexing means, a digitation mechanism effective to enter values determined by said value indexing mechanism into said product register, and power means for operating said digitating means and said shifting means selectively, a multiplication mechanism comprising ordinarily arranged and differentially positionable multiplier storage members, means controlled by said value indexing mechanism for differentially positioning said storage members, a restore shaft extending along said storage members, ordinarily arranged clutches adapted to clutch said restore shaft to said storage members, normally disabled means for incrementally rotating said restore shaft in a direction to return said storage members towards a "0" position, a cam shaft, cams mounted on said shaft for controlling the operation of said clutches, said cams being so constructed and arranged as to enable one only of said clutches at one time, means for incrementally rotating said cam shaft, a sensing mechanism associated with said storage members and operative to sense a "0" value position of the storage member that is clutched to the restore shaft, a multiply key, means operated by said key for enabling the incremental rotation of said restore shaft, means operated by the sensing mechanism when sensing a "0" condition of the storage member clutched to the restore shaft to disable the incremental rotation of said restore shaft and to enable the incremental rotation of said cam shaft, a second "0" sensing means effective to sense a "0" value position of all of said cams, and means operated by said second sensing means for terminating operation of said power means and for restoring said cam shaft to its original position.

6. In a calculating machine having a value indexing mechanism for storing a multiplicand value, a product register, means for shifting said product register relative to said value indexing means, a digitation mechanism effective to insert values determined by said value indexing mechanism into said product register additively or subtractively, power means for operating said digitating means and said shifting means selectively, a set of ordinarily arranged storage dials, means for inserting values into said storage dials from said indexing mechanism or said product register, a multiplier mechanism including an auxiliary keyboard, multiplier storage members differentially set by said keyboard and control keys for sequentially operating said digitating mechanism additively or subtractively under the control of said multiplier storage members, an auxiliary multiplication mechanism comprising a rotatable shaft extending along said storage dials, ordinarily arranged zero-cam members rotatably mounted on said shaft and each operatively connected to the coordinal storage dial, ordinarily arranged clutches adapted to clutch said shaft to said zero-cam members, means for incrementally rotating said shaft in a direction to return said zero-cam members toward a "0" position, a zero-sensing member associated with each of said zero-cam members and operative to sense a "0" value position of the coordinal zero-cam member, a control shaft, control cams mounted on said shaft for controlling the operation of said clutches and said zero-sensing members, said cams being so constructed and arranged as to enable one only of said clutches and zero-sensing members at one time, means for incrementally rotating said cam shaft, an auxiliary multiply key, means operated by said auxiliary key for disabling operation of the first multiplier mechanism and for enabling the incremental rotation of said shafts, and means operated by a zero-sensing member when sensing a "0" condition of the coordinal storage dial and cam member to disable the incremental rotation of said feed shaft and to enable the incremental rotation of said cam shaft.

7. In a calculating machine having a value indexing mechanism, a product register, digitation means for entering a value determined by said indexing means into said product register, means for shifting the relative ordinal

56

positions of said product register and said value indexing means, a cyclically operative drive means for operating said digitation means and said shifting means selectively, a plurality of ordinarily arranged storage dials, and means for entering multiplier values from said value indexing mechanism or said product register into said storage dials, the combination which comprises a rotatable shaft, ordinarily arranged cams rotatably mounted on said shaft and respectively geared to the coordinal storage dials, means operated by said drive means for incrementally rotating said shaft, ordinal clutches for connecting said cams to said shaft, means for sequentially operating said ordinal clutches whereby one only of said clutches will be engaged at one time, means for sensing the return of an operating cam to a "0" position, means operated by said sensing means for disabling said feed member and the operative one of said ordinal clutches, for operating said shifting means, for operating said sequentially operating means to enable the adjacent order clutch, and for initiating the reoperation of said feed member, means for sensing the "0" position of all of said cams, and means operated by said second sensing means for terminating operation of said drive means.

8. In a calculating machine having a value indexing mechanism, a product register, digitation means for entering a value set in said indexing means into said product register, a cyclically operative drive means for operating said digitation means, and means for shifting said product register relatively to said value indexing means, the combination comprising a rotatable shaft; a plurality of ordinarily arranged storage cams rotatably mounted on said shaft; means for entering multiplier values into said storage cams; restoring means including a feed member for rotating said shaft; means operated by said drive means for incrementally operating said feed member, and ordinal clutches for connecting said feed member to said storage cams to return said storage cams toward a "0" position; means for sequentially operating said ordinal clutches whereby only one of said clutches can be engaged at any time; means for sensing the return of an operating one of said storage cams to a "0" position; means operated by said sensing means for disabling said feed member and the operative one of said ordinal clutches, for shifting said product register, for enabling an adjacent order clutch, and for enabling the reoperation of said feed member; means for sensing the "0" position of all of said storage cams; and means operated by said last mentioned sensing means for terminating operation of said drive means and for returning said sequential operating means to its original condition.

9. In a calculating machine having a value indexing mechanism for storing a multiplicand value, a product register, means for shifting said product register relative to said value indexing means, a digitation mechanism effective to enter values determined by said value indexing mechanism into said product register, and power means for operating said digitating means and said shifting means selectively, a multiplication mechanism comprising a rotatable shaft, a set of ordinarily arranged storage cams rotatably mounted on said shaft, means for inserting multiplier values into said storage cams, a normally disabled feed means for incrementally rotating said shaft in a direction to return said storage cams toward a "0" position, ordinarily arranged clutches adapted to clutch said common shaft to the coordinal one of said cams, a cam shaft, ordinarily arranged control cams spirally mounted on said shaft for controlling the operation of said clutches whereby said control cams are operative sequentially to enable one only of said clutches and sensing members at one time, means for resiliently biasing said shaft to a position in which the lowest order cam is effective to enable the lowest order clutch, normally disabled means for incrementally rotating said cam shaft, a latch for holding said cam shaft in an adjusted position, a first zero-sensing member associated with each of said cam members and operative to sense a "0" value position of the coordinal cam

member, a second zero-sensing means for sensing a "0" value position of all of said cam members, a multiply key, means operated by said key for enabling the incremental rotation of said feed shaft, means operated by an operative one of said sensing members when sensing a "0" condition of the coordinate cam member to disable the incremental rotation of said feed shaft and to enable the incremental rotation of said cam shaft, and means operated by said second sensing member for terminating operation of said power means and for releasing said latch.

10. In a calculating machine having a value indexing mechanism for storing a multiplicand value, a product register, means for shifting said product register relative to said value indexing means, a digitating mechanism effective to enter values determined by said value indexing mechanism into said product register, and power means for operating said digitating means and said shifting means selectively, a multiplication mechanism comprising ordinarily arranged and differentially positionable multiplier storage members, means controlled by said value indexing mechanism for differentially positioning said storage members, a shaft extending along said storage members, ordinarily arranged zero-cams rotatably mounted on said shaft, ordinarily arranged clutches adapted to clutch said shaft to said zero-cams, normally disabled means for incrementally rotating said restore shaft in a direction to return said zero-cams toward a "0" position, a control cam shaft, control cams mounted on said shaft for controlling the operation of said clutches, said cams being so con-

structed and arranged as to enable one only of said clutches at one time, means for incrementally rotating said control cam shaft, a sensing mechanism associated with said storage members and operative to sense a "0" value position of the storage member that is clutched to the restore shaft, a multiply key, means operated by said key for enabling the incremental rotation of said restore shaft, means operated by the sensing mechanism when sensing a "0" condition of the storage member clutched to the restore shaft to disable the incremental rotation of said restore shaft and to enable the incremental rotation of said cam shaft, a second "0" sensing means effective to sense a "0" value position of all of said cams, and means operated by said second sensing means for terminating operation of said power means and for restoring said cam shaft to its original position.

UNITED STATES PATENT OFFICE
CERTIFICATE OF CORRECTION

Patent No. 3,107,851

October 22, 1963

Arthur J. Malavazos et al.

It is hereby certified that error appears in the above numbered patent requiring correction and that the said Letters Patent should read as corrected below.

Column 3, lines 18 and 32, for "mechanism", each occurrence, read -- mechanisms --; column 9, line 30, for "accumultor" read -- accumulator --; column 10, line 41, for "om" read -- of --; column 12, line 30, for "descripiton" read -- description --; column 14, line 24, for "lineal" read -- linear --; column 23, line 38, for "belcrank" read -- bellcrank --; line 72, for "effected" read -- effective --; column 24, line 18, for "auxiliary" read -- auxiliary --; line 60, for "haft" read -- shaft --; column 29, line 59, for "nonsildably" read -- nonslidably --; column 34, line 5, after "50" insert a period; column 37, line 36, for "othrewise" read -- otherwise --; column 40, line 16, for "ptwl" read -- pawl --; column 43, line 24, for "plan" read -- plane --; line 50, after "rocking" insert -- of --; column 44, line 60, before "notches" insert -- opposed --; column 45, line 25, for "operaitve" read -- operative --; column 50, line 32, for "multiplican" read -- multiplicand --; line 35, for "73" read -- 735 --; line 75, after "register", second occurrence, insert a comma; column 52, line 18, after "thereby" insert -- enable --.

Signed and sealed this 26th day of May 1964.
